UNITED STATES PATENT OFFICE.

CHARLES P. TOPPING, OF NORTH TONAWANDA, NEW YORK, ASSIGNEE TO BUFFALO BOLT COMPANY, OF NORTH TONAWANDA, NEW YORK. A CORPORATION OF NEW YORK.

METAL-WORKING MACHINE AND METHOD.

Application filed October 3, 1923. Serial No. 666,241.

My present invention is shown as embodied in a machine for making nuts, but it is obvious that many of its features are applicable to other metal working operations.

The machine is automatic in the performance of a considerable number of successive operations and while there is special interrelation and combination between the various 10 cooperating groups of elements, certain of the features are capable of performing their special functions separately or in combinations where some of the operations are omitted or some of them are performed by hand so that the machine is but partially automatic.

Many of the features of operation are of particular advantage in connection with the making of very heavy nut blanks and concern 20 punching, cutting and trimming of the blank by successive operations whereby the violence necessarily exercised upon the heavy metal is productive of the least possible distortion, thereby minimizing the power and number of steps required for perfecting the blank. Obviously, however, the methods which are so particularly advantageous for heavy material are also advantageous in connection with lighter material, 25 since the perfection of form and certainty of operation of the mechanisms are quite as important for the smaller nuts as for the larger.

As a complete machine, one of its most 30 important features is the general organization, whereby the machine, so to speak, stands on edge in such fashion that all of its metal working parts are readily and conveniently accessible from one side of the machine, which may be called the face or front. There are thus accessible, the piercing, cut-off and trim punches and dies, a rotary transfer mechanism and a turret indexing carrier and the successive finishing tools. 40 Even the automatic mechanism for feeding the bars or blanks to the machine, though located on the reverse face of the machine, are controllable from the front.

The face of the indexing turret mechanism is preferably fully exposed by supporting it in a single massive overhung bearing located at the rear of the machine. Dispensing with an outside bearing at the front of the machine makes the tools readily accessible for easy adjustment or replacement, 55 although as a matter of fact the conveniences of the organization are such that if desired a front bearing could be employed.

On the other or rear face of the machine are readily accessible all of the cams, shafts, 60 gears and other machine elements whereby the successive operating parts are driven in properly synchronized relation.

These are all operated from a single source of power by substantial connecting shafts, 65 links, etc., whereby it is made impossible for the groups of mechanism to get out of synchronism.

The novel groups of mechanism which are thus combined include the following: 70

There is an intermittently operated roller feed whereby the bar is presented step by step to the piercing cut-off and trim mechanism. In prior devices of this sort the intermittent rotation has been accomplished by 75 some form of pawl and ratchet mechanism. In practice it is found that even when the ratchets are made with teeth as fine as practicable or even when differential tooth ratchets and multiple pawls are used the leeway 80 for lost motion before a pawl engages its ratchet is too great and when the machine is used for various lengths feeds as where the same machine is successively employed for larger and smaller nuts, the punch, cut-off and trim mechanisms have to be specially 85 spaced in order to insure perfect registry and accuracy of performance of each of the three successive operations on the same blank; and there is also necessarily a slightly greater 90 waste of material between successive blanks.

I avoid these difficulties and secure a mathematical accuracy of reciprocating feed by dispensing with pawl and ratchet engagement and substituting therefor an 95 automatically operating friction clutch between the intermittent or oscillatory drive member and the one-way-rotating rolls, these parts being organized so that the friction clutch element is forced into positive non-slip engagement with the feed roll mechanism, prior to the beginning of the feed stroke of the oscillatory driving element and is completely unclutched and the rolls held stationary, at the end of said stroke and during the return stroke of the oscillatory 100 drive mechanism. With this organization of parts it is possible to adjust the throw of 105

the oscillatory drive element with perfect accuracy, and the clutch mechanism being toothless and capable of engagement in any angular relation whatever, the feed of the 5 rolls is absolutely predetermined and fixed so that for a given adjustment there can be no variation in the successive lengths of bar which it feeds into the machine, but the adjustment may be changed to vary the 10 lengths to any desired and accurately predetermined amount.

The first operation performed on the blank is the piercing. The next feed of the roll advances the bar but two such feeds 15 are necessary to bring the pierced hole in proper relation to the cut-off knife because of the spacing required for these tools. A supplemental reciprocating pusher registers the cut-off blank with the plunger of the 20 trimming dies. The movable pierce cut-off and plunger elements performing these three operations are located on a single slide so that they operate simultaneously on three different nut blanks of the advancing train. 25 This slide with its punches and the co-operating dies are so designed and the parts so positioned that they are readily accessible for adjustment, replacement or repair.

Operated by a cam on the slide which carries the above tools is an automatic clamping and punch stripping mechanism whereby the bar is perfectly clamped for the piercing and cut-off operation. The clamping at this 30 point is made extremely powerful, yet self-adjusting, for slight variations of thickness by causing the above described cam to effect only the opening movement of the clamp. The closing movement is effected by means 35 of a transverse wedge of relatively low pitch, which affords a positive non-slip backing against the thrust of the clamp; and the endwise sliding of said wedge to operative position is effected by means of a 40 spring of desired tension and applying a predetermined amount of wedge thrust regardless of the thickness of the material 45 which is clamped thereby.

The endwise accuracy of the feed being thus assured, the edgewise centering of the bar for the piercing operation is effected by 50 means of specially operating gauge clamps. An important feature of these centering gauges is that they comprise relatively heavy and therefore perfectly rigid, endwise reciprocating plunger bars. These are 55 automatically reciprocated to and from each other by very massive levers having extremely short work arms and relatively long power arms, the ratio on the machine shown 60 being approximately 16 to 1. These power arms are interconnected so that they thrust the gauge bars equally and oppositely thereby ensuring centering of the stock bar regardless of its thickness. Their adjustment 65 for a desired center is simply and accurately

accomplished by means of massive thrust screws whereby the respective lengths of the plunger bars may be independently increased or decreased. The short work arm and long power arm lever is actuated by an 70 oscillatory cam surface which takes effect at the extreme end of the power arm, and is of slight pitch. The result of this construction is that the gauge bars may be thrust towards each other with a power sufficient 75 to insure perfect centering and even to slightly spring or bend the bar to the centered position, if necessary, and yet the power required to operate the oscillatory 80 cam is extremely small. This makes it practicable to effect the operation of said oscillatory cam, to positively open the grip of the gauge bars while permitting the same to be closed non-positively but with the above described great power, by means of 85 relatively slight tension springs. With such spring closing, variable throw is automatically provided to take care of over size or under size stock, the proper centering of which is ensured by the above described interconnection.

While the matrix dies for trimming the blank admit of variations, I prefer to employ a plurality of them in tandem spaced apart a distance substantially less than the 90 thickness of a nut so that the plunger may reciprocate through a distance merely sufficient to engage and force one nut blank through the first die, but will nevertheless operate to force the nut blanks beyond it in 95 the train, through the remaining dies of the series. By making a plurality of trims, the amount of metal to be removed by each operation will be slight, the power required will be less and the trimmed surface 100 smoother.

The nut blanks emerging from the matrix dies may be more or less stuck together by the great pressure and by the metal dragged across from one to the other. Consequently 110 a very certainly operating mechanism is required to pick off the end blank and transfer it to the turret. The transfer mechanism which I employ for this purpose includes a spring clamp element which is 115 forced onto the end nut blank, reciprocated to pull away to separate said blank for the series, rotated through 180° and again reciprocated to drive the nut upon a stud mandrel carried by the turret index member. The 120 rotation through 180° is required because the nut blanks as they emerge from the matrix dies are naturally bulged or crowned on the emerging faces and more or less concaved on the rear faces and by rotating them 125 through 180° the rough crown is naturally presented outward toward the crowning tool which performs a later operation on the blank. Thus the work of this tool is likely 130 to be a shaping and flattening operation,

most of the convexing being localized at the corners of the head of the nut.

For rapid operation it is desirable that the transfer clamp be perfectly balanced, hence it is preferably made in the form of a complete cylindrical roll with circular spring flanges. An important feature of the invention is having the reciprocation of the carriage for this clamp, cause the 180° revolution. According to one method this is accomplished by providing the clamp with a 180° segmental gear having two end flats in combination with a short length of stationary rack rolling with flat slide surfaces at each end. The two flats serve as locks to prevent further rotation in either direction, during the beginning and end portion of each stroke, that is, while the clamp is approaching its receiving and delivery points and the intermediate stationary rack causes the 180° rotation. As rapid operation is required for the transfer mechanism, the jar of engagement of the segment with the rack is likely to be violent, moreover, the distance of the throw required for the transfer mechanism is not accurately predeterminable at either the receiving end or the delivery end of the stroke, because of the differences of thicknesses of the nuts and slight changes in diameter of the piercing punch necessarily resulting from wear of the punches and slight variations in the thickness of the material. For instance, if the punch is worn, the hole in the nut will be a little smaller and the nut cannot be driven so far onto the stub mandrel of the indexing mechanism as it could when the punch was new and making perfect full size holes. In order to permit this variation of throw and to somewhat temper the shock of impact of the tumbling segment with the rack an important feature of my invention consists in interposing a two-way yielding spring element in the train of driving mechanism which reciprocates the transfer.

While interposition of springs either at the point shown or at any other desired point between the rotating gear and the drive mechanism, substantially decreases shock and permits increase of speed of operation, it will be found that rotating shock can be completely eliminated by utilizing a radius arm on the rotating clamp and guiding the free end of said radius arm by a cam of quasi epicycloidal shape. It will be recognized that such cam and the contact member on the said radius arm constitute in effect a one-tooth gear of peculiar sort such that starting and stopping of the 180° revolution in accordance with the epicycloidal shaped cam is ideally gradual and is substantially free from all possibility of rotary shock.

An important feature of the invention is the use of stud mandrels on the turret to present the blank to the successive finishing

tools. This mandrel has a very slight taper of say one thousandth to three thousandths of an inch and the blank is driven on to it as far as it will go under the inertia impact of the transfer mechanism.

An important feature of the stud mandrels is that all of the finishing operations on the nut are made while the nut remains immovable on the mandrel. The mandrel is perfectly adjusted to position and accurately indexed to each of the successive crowning and trimming dies, thereby producing a nut with the hole exactly centered, whereas machines commonly employed for this work have no means of correcting any error in location of hole relatively to the sides of the nut. In some cases there is no attempt to prevent or to correct eccentricity and in some cases the nut is transferred from tool to tool by spring fingers working on outside of nut, which cannot ensure the desired accuracy.

At the base of the stud there is an annular fillet onto which the blank is driven by the crowning tool, thereby pressing or forging a conical end countersink affording a smooth finish for the thread at the base of the completed nut.

At the same time, there is a concave end or countersink formed at the other end of the hole done by die, this double countersink being formed without extra cost, tools or handling produces a better threaded nut without the usual burr formed at the end of the thread; also it aids in entering of tap, etc.

My invention involves various other features of importance which will be pointed out hereinafter or will be apparent from a consideration of the preferred embodiment illustrated in the accompanying drawings. In these drawings:

Fig. 31 is a section on the line 31—31 of Fig. 30.

It will of course be understood that the 50 specific machine illustrated in the accompanying drawings, and hereinafter described in detail, constitutes only one embodiment of my invention, and that various changes may be made in the details of construction and the general arrangement of the parts without departing from the scope 55 of my invention. I therefore desire the following description as well as the drawings to be considered as illustrating, rather than limiting, my invention.

In order that the various operations of 60 piercing, cutting, trimming, feeding, transferring, etc., may be performed in proper timed relationship, all of the operating parts of the machine are driven from a single source of power. For this purpose I have 65 shown a main drive shaft 1 (Figs. 2, 3 and

28) mounted in suitable bearings and connected directly or indirectly to the various operating parts. This shaft may be driven from any suitable source of power, that illustrated (Figs. 2 and 3) including a main 70 gear 2 meshing with a pinion 3 on a shaft forming a continuation of the armature shaft of an electric motor, as suggested in dotted lines in Fig. 3. If gear reduction is desired, the shaft of the pinion 3 may be 75 provided with a gear 4 meshing with the drive pinion of an electric motor also illustrated in dotted lines in Fig. 3.

The main drive shaft 1 is provided with a main cam 5 for operating the main slide 80 which carries the various punches for roughing out the nut, a secondary cam 6 for returning the main slide and for operating the dies associated with the turret, and a bevel gear 7 for driving a bevel gear 8 on a 85 side shaft 9, which latter operates the feed mechanism, the transfer mechanism, the turret and other parts.

The punches for piercing, cutting off and trimming the slug are carried by a main 90 slide 10 (Figs. 1, 5 and 7) which moves back and forth in the general direction of the length of the machine, and in a horizontal plane. This main slide is operated by the main cam 5, the operating connections including a main roller 11 mounted in suitable bearings on the slide and engaging with the main cam 5. The cam acts directly on the roller to impart the power stroke to the main slide and its punches while auxiliary 100 mechanism acts to give to the slide its return stroke. This slide return mechanism includes a roller 12 mounted on an arm 13 rigid with a rock shaft 14. The roller engages the cam 6 on the opposite side of the 105 shaft 1 from the roller 11. The portion of the main slide having the bearing for the roller 11 is provided with a bracket 15 which is connected by draw rods 16 to pivot pins 17 carried by lever arms 18 also rigid with the rock shaft 14. The rollers 11 and 12 may be adjusted toward and from each other to properly engage the main cam and secondary cam respectively by saddle washers 19 and nuts 20 and the cams are of such contour as to engage both rollers at all times. The rollers 11 and 12 are at fixed distances apart and each acts as a pull-back for the other.

The main slide is supported by the main 120 frame (Fig. 7) and is preferably guided and held against lateral or vertical movement by undercut saddle or guiding flanges 21 which are bolted to the main frame, and which are adjustable toward and from each other to 125 provide an accurate fit, to adjust the slide laterally, and to take up for wear.

The punches for roughing out the slug and which are carried by the main slide include a piercing punch 22, a cut-off punch 130

23, and a trimming punch 24 (Figs. 5, 7 and 14). The piercing punch is carried by a punch holder 25 which is held in position by a wedge 26 disposed between this holder and the cut-off punch 23. The cut-off punch is held in position by a clamp 27 and the trimming punch is held in position by a similar clamp 28. The three punches are endwise adjustable in respect to the slide, and are accurately positioned and backed up by vertically adjustable wedges 29.

The operating ends of the three punches are in different transverse planes, and the material is fed not only transversely of the machine, that is, at right angles to the direction of movement of the punches, but is also moved in the direction of movement of the punches during the successive operations of cutting off and trimming, as is shown particularly in Fig. 14.

Stripper mechanism is employed for clamping the stock during the piercing operation and for facilitating the withdrawal of the piercing punch. The stripper mechanism shown in Fig. 8 and Figs. 1, 4, 5 and 6, includes a stripper 30 pivotally mounted on a pivot bar 31 mounted in a bracket 32 on the main frame. This bracket is adjustable to accurately position the stripper arm in respect to the stock and the piercing die. Bracket 32 may be supported from the main frame upon the screws 32^a indicated in dotted lines in Figure 8, passing through slots (not shown) in the bracket. The bracket is adjustable longitudinally of the machine by an adjusting screw 32^b to move the stripper toward and from the work in order that the work engaging portion of the stripper may be maintained parallel with the face of the die 140 for all thicknesses of stock. The arm has an aperture 33 through which the piercing punch may pass and on the side of the stripper arm adjacent to the stock is a clamping face for engagement with the stock or bar A from which the nuts are to be made.

The stripper arm is normally freely suspended from its pivot pin 31 except during the piercing operation and the withdrawal of the piercing punch. During those operations the stripper arm is held tightly against the stock.

With the ordinary non-articulated stripper in use on the majority of present machines, the stripper gives free passage to the stock bar with a $\frac{1}{16}$ " or more freedom for the bar both flat and edge ways. This makes it possible for a twisted bar to enter. When the piercing punch hits such a bar it temporarily takes out the twist during the period of piercing and a part of the period of withdrawal of the piercing punch. During the latter part of the withdrawal, however, the twisted bar attempts to and does to quite an extent, return to its natural twisted form, nipping the end

of the piercing punch and pulling off or breaking the end of the latter. As contrasted with this, my articulated stripper, assisted by the pressure of the piercing punch, will press a twisted bar flat against the piercing die and it will be held there by the non-yielding stripper until the piercing punch is entirely out of the stock, thus saving many broken punches.

Another feature is that my articulated stripper allows more room for the passage of the bar so that it can be fed more freely and accurately the exact width of the desired blank.

Still another feature of this stripper is that it may be easily moved out of the way for setting the tools and then quickly returned to position. Preferably the stripper is slidable along the bar 31 and capable of being locked in any desired position thereon by suitable latching mechanism (not shown).

The articulated stripper, together with the centering fingers (hereinafter described) permit freer feeding of the stock, with great accuracy in location of the hole and the cut-off of the blank. They also make practical the use of relatively narrow stock of width equal only to a minimum diameter of a nut, thus considerably reducing the amount of scrap produced.

For operating the stripper arm there is provided a plunger 34 (Figs. 5 and 8) movable back and forth in the direction of movement of the piercing punch and main slide. The plunger is operated by suitable mechanism from the slide, and in proper timed relationship to the movement of the latter. This operating mechanism includes a bar 35 slidable in suitable guides in the main frame, and in a direction at right angles to the plunger. The plunger and bar have co-operating cam faces (Fig. 5), the cam face on the bar 35 being of low pitch, for instance, about 14° to general direction of the length. The outer end of the bar is formed as a rack for engagement with a toothed segment 36 on a pivoted arm 37, carried by a sleeve 38 (Figs. 1, 5 and 7) mounted on a stud bolt 39 on the main frame adjacent to one edge of the main slide. The sleeve 38 carries a second arm 40 which has a roller 41 engaging with a cam 42 on the main slide. The rack bar 35 is provided with a suitable spring 43 which holds the roller 41 in engagement with the cam 42, and is of such strength that when the main slide moves to the left, as indicated by the arrow in Fig. 5, to perform the piercing, cutting and trimming operations, it pulls the rack bar 35 inwardly so that the cam on said bar follows up the plunger 34 and holds it against the lower end of the stripper arm 30, and clamps the stock from which the nut is to be made.

The engagement of the plunger with the stripper arm may be controlled by an adjust-

ing screw 44 (Fig. 8). As the main slide returns, the cam 42 pulls back the rack bar against the action of the spring 43 so as to permit the return movement of the plunger 34. This return movement is accomplished by a spring 45 engaging with the forward end of the plunger.

In operation, the punch forces the stock against the die and may even straighten the stock if it be twisted, while the spring 43 causes the plunger 34 and the stripper to follow the stock to final position and takes care of slight irregularity in the thickness of the stock. In withdrawing the punch, the low angle cam of the bar 35 offers what is in effect an abutment or shoulder to prevent the withdrawal of the plunger 34 and positively holds the stock in place. After the punch is out of the stock, the cam 43 pulls back the bar 35 against the action of the spring 43 and lets the spring 45 act on the plunger 34 and release the stripper and stock.

Before the piercing operation by the punch 22 the stock A is also centered and clamped against vertical movement. For accomplishing this there are provided upper and lower centering fingers 46 and 47 (Fig. 8) carried by upper and lower plungers 48 and 49 guided in the main frame. These fingers are movable toward and from each other so as to hold the stock during the piercing operation and to free it from friction for feeding movement. For operating the two plungers 48 and 49, and their centering fingers, there are provided upper and lower rock shafts 50 and 51 (Figs. 6 and 8) having offset or eccentrically disposed abutments 52 and 53 for engagement with adjusting screws 54 and 55 upon the opposed ends of the plungers 48 and 49. When these rock shafts are rotated in opposite directions the abutments engage with the adjusting screws to force the plungers toward each other and force the centering fingers 46 and 47 into engagement with the stock. Upon the return rotation of the rock shafts the lower plunger may drop slightly by gravity while the upper plunger may be raised by a spring 56.

For oscillating these rock shafts the upper shaft is provided with a lever arm 57 connected by a rod 58 to a lower lever arm 59 on a sleeve 60 on a stud bolt 61 carried by the main frame (Figs. 4 and 6). The sleeve 60 is provided with a rack segment 62 meshing with a rack segment 63 rigidly connected to the lower rock shaft 51. Thus by raising the arm 57 the upper rock shaft is rotated (clockwise, Fig. 8, counter-clockwise, Fig. 4) to force down the upper plunger 48, and at the same time the rod 58, the sleeve 60 and the meshing rack segments 62, 63 rotate the lower rock shaft 51 in the opposite direction to force upwardly the lower plunger 49. The upward movement of the lower plunger is always equal to the

downward movement of upper plunger, thus centering the stock correctly regardless of size.

For operating the centering fingers 46 and 47 in proper timed relationship to the action of the piercing die there is provided driving connections to the side shaft 9. The bevel gears 7 and 8 which drive this shaft are of the same size so that the side shaft makes one revolution for each revolution of the main shaft 1. The side shaft 9 drives a transversely extending shaft 64 (Figs. 15 and 18) by means of bevel gears 65, 66 which are also of the same size so as to give the cross-shaft 64 one revolution for each revolution of the main shaft. On this cross-shaft 64 there is provided a cam 67 which engages with a roller 68 on a lever 69 pivoted on a stud bolt 70 (Fig. 4). The upper end of this lever is provided with a cam face 71 engaging with a roller 72 on the outer end of the arm 57. A spring 73 is secured to the lever 69 so as to retain the roller 68 in contact with the cam 67. The cam face 71 is of such form that as the lever arm 69 moves back and forth, the arm 57 is raised and lowered. The extent of this movement is sufficient to grip and release the stock between the centering fingers 46, 47, and the shape and angular position of the cam 67 is such that the centering fingers release the stock at the proper time to permit the endwise feeding movement of the latter.

The spring 73 is the source of power for moving the centering fingers into position and it takes care of any irregularity in the width of the stock. It acts with the desired force due to the leverage of the arm 69, the angle of the cam face 71 and the length of the arm 57 in respect to the distance of the plunger 48 and 49 from the centers of the rock shafts. The cam 67 merely permits the spring 73 to act at the proper time to do the centering and clamping operation, and then positively forces the arm 69 back against the action of the spring 73 to release the stock.

The bar A from which the nuts are to be made, and which is intermittently gripped and released by the centering fingers 46, 47 and the stripper arm 30, is intermittently fed endwise between successive operations of the punches. The feeding mechanism is designed to positively grip the bar, feed it endwise for an exact and pre-determined distance, and then rigidly hold it during the next punching operation. Speed and accuracy of feeding are very important.

The feeding mechanism illustrated (Figs. 4 and 18 to 22) includes a pair of feed rolls 75, 76 for gripping the bar therebetween. One of the feed rolls, 75, is keyed to a vertical spindle 77 mounted in suitable bearings in a bracket 78 (Fig. 20) secured

to the main frame. The other feed roll 76 is keyed to a spindle 79, the bearing sleeve 80 for which is pivotally connected to a lug 81 of the bracket 78 (Fig. 19). The pivot pin 82 is parallel to the two spindles and permits the feed roll 76 to be moved toward and from the feed roll 75. This permits the gripping of the stock between the feed rolls with any desired degree of pressure, and also permits the feed rolls to be separated to interrupt the feeding operation. For adjusting the two feed rolls toward and from each other, the bracket 78 and the hinged gate or sleeve 80 are provided with outwardly extending lugs within which is mounted a connecting rod 83. The rod at one end has pivoted thereto a lever arm 84 which has an eccentric disk 85 engaging with the lug on the bracket 78. On the opposite end of the rod is a cushioning spring 86 which is compressed as the rod is pulled endwise by the eccentric disk and the two feed rolls are forced together. The spring 86 takes care of variation in the thickness of the stock and by exerting greater or less pull on the rod 83 the pressure of the feed rolls on the stock is adjusted. Intermediate of its ends the rod carries a second spring 87 which acts on the rod 83 and the stationary member 78 to separate the rolls when the eccentric disk is rotated clockwise from the position shown in Fig. 18. The bracket 78 carries an arm or flange 88 for supporting the stock between the feed rolls.

For moving the lever arm 84 to open or close the rolls, and thus grip or release the stock, and to adjust the pressure of the feed rolls on the stock, there is provided a link 89 pivotally connected to the outer end of the lever arm 84, and to a lever arm 90 secured to a transversely extending rock shaft 91. This rock shaft is mounted in suitable bearings 92 carried by the main frame and extending to the opposite side of the latter where it is provided with an operating crank 93 (Figs. 1 and 7).

For rotating the two feed roller spindles 77 and 79 in unison and for preventing any back lash or lost motion, the two spindles are provided with two pairs of intermeshing gears 94. The upper gear of each pair is of the same pitch diameter as the lower gear, but the teeth are staggered as is clearly shown in Fig. 18. These two pairs of gears with staggered teeth have the effect of one pair of gears with twice the number of teeth but they have the advantage of large sizes and strong teeth not easily broken and permit greater range of adjustment of the gears toward and from each other without unmeshing or giving undue lost motion. By means of these gears the spindle 79 is driven from the spindle 77 and the two feed rolls rotate in opposite directions. The adjustment of the feed rolls toward and from

each other to release or grip the stock is not sufficient to move the gears out of mesh.

For intermittently rotating the spindle 77 of the feed roll 75 there is provided clutch mechanism (Fig. 20) including an upper 70 clutch member 95, a middle clutch member 96 and a lower clutch member 97. The upper clutch member is rigidly secured to the spindle and may also have directly secured to it the gears 94 of this spindle. The lower 75 clutch collar is keyed to the spindle but is free to move endwise thereof. The middle clutch member 96 has oppositely facing conical parts for clutching engagement in conical sockets of the upper and lower clutch 80 members, and is freely rotatable on the spindle 77 when free of the other clutch members. This middle clutch member is supported by a collar 98 secured to the spindle and so positioned as to permit the middle 85 clutch member to drop free of the upper clutch member when the lower clutch member is lowered out of engagement with the middle clutch member.

Means are provided for raising and lowering the lower clutch member to cause the three clutch members to interengage, and separate means is provided for rotating the middle clutch member to thereby rotate the spindle when the clutch is engaged. Means 90 may also be provided for holding the spindle against rotation when the clutch is disengaged. These several operating mechanisms are driven from an auxiliary shaft 100 95 (Figs. 4, 18, 19 and 21) vertically disposed 100 and mounted in suitable bearings carried by the main frame. This shaft is driven by a pair of equal sized bevel gears 101 and 102, from the side shaft 9, which, as previously noted, is driven from the main drive through 105 the gears 7, 8.

For oscillating the middle clutch member 96 the latter is provided with an arm 103 which is connected by a link 104 to a lever arm 105. The latter has its opposite end mounted on a pivot pin 106. The shaft 100 is provided with a cam 107 which engages a roller 108 mounted on the lever arm 105 so as to swing this arm back and forth during the rotation of the shaft 100. The link 104 is adjustable lengthwise of the arm 103 by a pin 109 in a slot, so that any desired angle of oscillation may be imparted to the arm 103 and the middle clutch member carrying the latter, and thus the length of stock fed at each operation may be varied at will and the greatest accuracy of feed obtained. The return movement of the parts 103, 104 and 105 is effected by a spring 105a.

For positively locking the spindle against rotation except when driven by the clutch, there is provided a brake band 111 encircling the upper clutch member. A brake-operating lever 112 is mounted on a stud 113 and is connected to opposite ends of the

brake band by bolts 114 and 115 which are provided with suitable adjusting nuts so that as the outer end of the lever is swung out from the main frame (Fig. 21) the brake band is tightened. The shaft 100 is provided with a cam 116 engaging with a roller 117 on the outer end of the brake lever 112. The lever is also provided with a spring 118 which holds the roller in engagement with the cam and acts to tighten the brake band when the cam rotates to such position as to permit the outward swing of the outer end of the lever 112.

For opening and closing the clutch whereby the oscillation of the middle clutch member 96 rotates the feed rolls, means are provided for raising and lowering the lower clutch member 97. This mechanism (Figs. 20 and 22) includes a pair of collars or sleeves 119 and 120 telescoping by screw thread connections whereby a rotation of one collar in respect to the other increases or decreases the total effective length of the two collars or sleeves. The upper end of the inner collar 120 supports the lower clutch member 97 by means of a ball bearing 121 and the lower end of the outer collar is supported by an adjusting collar or stop 123 on the lower end of the spindle 77, by a ball bearing 122. One of the collars, as for instance the inner collar 120 is held against rotation. As shown, it has a lug portion 124 secured to a bracket 125 on the main frame. The outer collar 119 has a peripherally toothed segment portion 126 meshing with a rack bar 127. This rack bar has one end secured to a lever arm 128 by a pivot pin 129 and the other end of the link is connected by a pivot pin 130 to a bracket 131 on the lower bearing for the vertical shaft 100 (Figs. 18, 19 and 21). The shaft 100 has a third cam 132 for engaging with a roller 133 on the lever arm 128, and this roller is retained in contact with its cam by a spring 134 connecting the bracket 125 to the pivot pin 129. As the cam 132 rotates, the lever arm 128 is swung back and forth about its pivot pin 130, and the rack bar 127 is caused to reciprocate and thereby oscillate the outer collar 119. By reason of the threaded connection between the collars such oscillation of one in respect to the other causes a raising and lowering of the lower clutch member 97 and the intermittent gripping and releasing of the oscillatory middle clutch member 96 to the feed roll spindle 77.

It will be noted that the shaft 100 which is given one rotation for each rotation of the main drive shaft 1, has three separate cams 107, 116 and 132 thereon. One of these oscillates the middle clutch member, another applies and releases the brake band on the upper clutch member, and the third engages and disengages the clutch members. The three cams are so designed and have their

throws in such angular spacing or timed relationship that the single rotation of the shaft 100 operates the parts of the feed mechanism through the following cycle starting with the parts in the position shown in Fig. 21.

The rotation of the cams in a counter-clockwise direction will hold the oscillatory clutch member stationary while the shaft is rotated through approximately 90°. In the meantime the roller 117 has moved down the inclined surface of the cam 116 so as to apply the brake, and as soon as the brake has been applied the roller 133 moves up the incline of the cam 132 to drop the lower clutch member and open the clutch. After the clutch has been opened the roller 108 reaches the end of the circular part of the cam 107 and begins traveling down the incline so as to oscillate the middle clutch member in a clockwise direction, as viewed in Fig. 21. It will be noted that during this return movement, the feed rolls are locked by the brake and the clutch member is open. By the time the oscillatory clutch member has reached its opposite limit of movement the clutch closing cam begins operation, and by the time the clutch is closed the brake operating cam comes into operation and opens the brake. The cam 107 has by this time rotated to such a position that it begins to swing the lever arm 105 to the right, thus positively rotating the middle clutch member and through it the remainder of the clutch and the spindle, and effecting a feeding movement of the stock. This completes the cycle and brings the parts again to the position shown in Fig. 21.

From the foregoing it will be seen that the cycle of operations of the three cams on the shaft 100 is in the following order. Closing the brake, opening the clutch, returning the middle clutch member, closing the clutch, opening the brake, and feeding the stock. This mechanism thus gives a very accurate feeding movement through an exact distance, positively locks the feed rolls in position during the operation of the punches, and holds the feed rolls locked against return movement during the return oscillation of the middle clutch member.

It will be noted that my improved feed mechanism is toothless, that is, the oscillatory clutch member may be caused to engage the one way rotating clutch member in any desired position and while the latter is stationary, rotate through any desired angle and then release while the other is stationary. Thus there is no slipping in engaging or releasing and the distance through which the stock is fed and the point to which it is fed may be predetermined with the greatest accuracy which is not possible in any form of ratchet or toothed mechanism where the width of a tooth or a definite fraction there-

of is the limit of accuracy in the control of the feed. For larger or smaller nuts it is merely necessary to properly space the piercing and cut-off punches and their dies and 5 adjust the rod 104 to the proper point along the length of the arm 103.

It will be apparent that the oscillation of the middle clutch member in one direction causes a feeding movement of the feed rolls 10 and the return movement does not return the feed rolls because during the movement in one direction the clutch parts are engaged, and during the return movement they are separated. Therefore, in order to stop or start the 15 feeding of the stock at any time desired, I provide means for controlling the engagement of the clutch member. The simple mechanism illustrated for accomplishing this result is a stop for preventing the rotation 20 of the outer threaded collar 119 to close up the clutch. This will merely prevent the return of the rack bar to the position shown in Fig. 21 after the rack bar has been moved toward the left to the limiting position by 25 the cam 132. A very simple form of stop mechanism includes a throw-out lever 135 pivoted on the bracket 125, and having a terminal portion 136 movable into and out of the path of a lug or shoulder 137 on the 30 outer collar 119. The normal position of the stop lever is shown in Fig. 22, and the parts are here shown in the position which they occupy when the clutch is completely disengaged. By swinging the terminal portion 35 of the throw-out lever 135 into the path of the shoulder 137, the outer collar cannot be rotated by the spring 134 to close up the clutch. With the parts so engaged the oscillation of the middle clutch 40 member by the cam 107 will not impart any motion to the feed rollers. The shoulder 137 has a flange at its outer end to act as a keeper for the end of the lever 135 so that the lever cannot be moved out of engagement 45 with the shoulder except when roll 133 is at the top of the cam, the clutch is open and the middle clutch in one limiting position. Therefore, the parts cannot be released to give a part-way feeding movement to the 50 stock. The throw-out lever preferably extends transversely of the machine to the opposite side, and may there terminate adjacent to the crank 93 and be held in a guard 138. The throw-out lever for controlling 55 the rotation of the feed rolls and the crank 93 for adjusting the feed rolls toward and from each other, are thus conveniently placed on the same side of the machine.

The bar A from which the nuts are to be 60 made, is fed by the feed rollers 75, 76 in a direction substantially at right angles to the direction of movement of the main slide 10 (Fig. 14). The advance of the stock passes behind the stripper arm 30 and in front of 65 a piercing die 140 which is carried by a die

block 141. This die block is properly positioned in respect to the piercing punch 22, and the aperture 33 in the stripper arm, so that when the main slide is forced forwardly the piercing punch passes through the stock and into the die 140, forcing the slug A' ahead of it, and forming an aperture in the stock of a diameter corresponding to the internal diameter of the nut to be made. The slug drops out of the machine through 70 passage 140a. Adjacent to the piercing die 140 is a cut-off die 142 in proper alignment with the cut-off punch 23 of the main slide. The cut-off die and the piercing die are centered at distances approximately equal to 75 twice the diameter of the nut to be made from the stock so that the stock after being pierced by the piercing punch is thereafter advanced one step, where it remains integral with the end of the stock to prevent distortion of the latter while the piercing operation is being performed on the next blank. The next advancement of the stock brings the portion in which the first hole 80 was formed into proper centered position in 85 respect to the cut-off punch. The cut-off punch is of an outside shape approximating that of the nut to be made, and cuts off from the stock a nut blank B having a centrally disposed aperture therethrough previously 90 formed by the piercing die. The blank which is cut off is preferably longer than it is wide (see Fig. 6) as the sides cut by the die require more trimming to give a smooth 95 surface than do the sides which were formed by the sides of the stock.

It will be noted that the cut-off punch carries the blank through the cut-off die, and to a position out of alignment with the line of feed of the bar or stock A. The blank B, after being cut off, is forced between the opposite flanges 143 of a carrier 144, the terminal portion of which is shown in perspective in Fig. 13. This blank carrier 100 after receiving the blank B moves endwise 110 to carry the blank into proper operative position in respect to a series of trimming dies 145, 146, and 147. These dies are in alignment but are spaced apart and differ slightly in shape so that the blank as it is forced 115 through the three trimming dies in succession will have a small amount of metal removed by each, and thereby brought to the desired shape. These trimming dies are all carried by the die block 141, and they are in alignment with the trimming punch 24. The distance between the centers of the cut-off punch and the trimming punch is not material, as the carrier 144 may be given 120 any desired length of stroke to carry the blank from its position at the end of the cut-off punch into alignment with the trimming punch. The trimming punch 24 is provided with a slightly tapered centering pin 148 adapted to enter and substantially fit the 125 130

previously pierced aperture in the slug, and the face portion of the trimming punch directly encircling the base end of the centering pin may be rounded or beveled so as to 5 slightly chamfer or cone the edge at the end of the hole through the blank. The trimming dies are spaced apart as shown in Figs. 9 and 14, and the spaces between lead to a chute or passage 149 leading downward- 10 ly through the die block and the supporting portion of the main frame for the delivery of the trim.

The cut-off and trimming punches and dies are shown of a form to make hexagonal 15 nuts from a bar of a width corresponding to the minimum diameter of the nut. If a wider bar or smaller dies and punches be used, the punches and their coacting dies may be mounted with the maximum diameter, that is, the diagonal, transverse to 20 the bar. With either arrangement one punch and die may cut pairs of notches in opposite sides of bar between adjacent nuts preferably after the piercing and before the cut- 25 off. The specific form of these punches and dies may vary with the desires of the nut manufacturer and form no essential part of my invention.

The mechanism for actuating the carrier 30 144 to move the blank from cut-off to trim position, is operated from the cross shaft 64 which has previously been referred to as operating the cam faced lever 69 which controls the centering fingers. Said carrier 144 is pivotally connected at its outer end to a 35 lever arm 150 mounted on a rock shaft 151. (Figs. 4, 6 and 18). The opposite end of the rock shaft is provided with an arm 152 which is pivotally connected to a vertically 40 movable rod 153 terminating in a fork or yoke straddling the shaft 64 (Figs. 15 and 18). The shaft is provided with a cam 154 (Figs. 5 and 15) engaging with rollers 155 on the rod 153. By reason of this cam and 45 roller connection each rotation of the shaft 64 gives an up and down movement to the rod 153 and the latter through the rock shaft 151 and lever arm 150 impart a back and forth movement to the slug carrier. This 50 motion is positive both ways as distinguished from any of the other moving parts which have a cam actuation in one direction and a spring actuation in the return direction.

The die block is rigidly secured to the 55 frame of the machine and the various parts are adjustable to bring the dies into registry with the punches. As shown (Fig. 6) the die block 141 is mounted upon a pair of transversely extending superposed wedges 156, 157 which may be adjusted endwise to 60 vary the elevation of the die block. The holders for the cut-off and trimming dies are clamped in the main die holder, and the latter is secured to the frame by clamping bolts 158. Preferably the cut-off and

trimming dies are circular but have a flat side to engage a clamp which locks them against rotation.

Beyond the trimming dies the frame is 65 provided with a guide for the trimmed blanks (Figs. 9, 10, 11 and 12) extending through a portion of the main frame. This 70 guide includes a tube having a stationary section 159 and a longitudinally adjustable section 159^a which may be clamped in position in any suitable manner as for instance by means of a set screw (Fig. 9). Within the tube is a liner made up of a plurality of strips. In the stationary tube, 75 section 159, are upper and lower strips, 160 and 161, secured in place by screws (Fig. 10) and projecting into the adjustable tube section 159^a. The upper strip is preferably 80 shorter than the lower strip, the latter extending to or nearly to the end of the tube section 159^a. The stationary tube section 159 also has side strips 162 in alignment 85 with side strips 162^a which are rigidly secured to the tube section 159^a and project beyond the outer end of the latter. The outer ends of the strips 162 have their upper and lower edges cut away so that they 90 are of slightly less height than the nut blank guided thereby. Thus the outer tube section may be adjusted in and out to bring 95 the ends of the guide at any desired point and the nut in its outermost position in the guide will be supported at opposite sides but have its top and bottom surfaces exposed for engagement by the transfer mechanism hereinafter described. The blanks are forced through the guide in succession, and at all times the guide contains a plurality 100 of blanks; one reaching the delivery end each time one is forced through the last trimming die 147 into the entrance end of the guide. The number of blanks in the guide and the position of the outer surface of the outer one will vary with the thickness 105 of the stock from which they are made.

For carrying the successive blanks to the successive tools for performing various further or finishing operations there is provided a turret 163 (Figs. 1 and 16) carried by or integral with a transversely extending 110 shaft 164. The main bearing for the shaft includes a bushing 165 externally tapered and mounted in a stationary internally tapered sleeve 166. The bushing has longitudinal slits so that it may expand and contract and may be adjusted endwise by means of a nut 167 to maintain the proper bearing fit. The shaft is also mounted in a bushing 168 which is secured by a cap 169 in a bracket 170 carried by the main frame. For 115 adjusting the shaft endwise it is provided with a nut 164^a held between a ring 164^b and the end of the bearing. By rotating the nut the shaft is forced endwise. The 120 nut may have a slit and clamping means

to normally hold it against rotation in respect to the shaft. It will be noted that the turret is mounted as close as possible to the bearing as a result of my improved construction and that the entire turret is exposed to view and readily accessible.

For intermittently rotating the turret there may be employed an ordinary Geneva stop gear. As shown (Figs. 4, 15 and 16), the shaft 164 is provided with a radially slotted plate 171, and the transverse shaft 64 is provided with a pair of arms 172 connected by a roller 173 constituting the other element of the Geneva stop. Thus during each complete revolution of the transverse shaft 64 the turret shaft 164 is rotated through a part of a revolution and then stopped and locked stationary. The Geneva gear may be of any desired driving ratio depending upon the number of finishing operations which it is desired to impart to the blank while being carried by the turret. As shown, the Geneva disk 171 is provided with five radial slots which, in succession, receive 25 the roller 173. Thus the turret is given one complete revolution for each five rotations of the transverse shaft 64 and the main shaft 1.

For positively locking the turret shaft against rotation except when driven by the Geneva gear, the shaft may be provided with a disk 174 (Figs. 4 and 16), having a series of recesses 175 in its periphery. The bracket 170 provided with a slide-way 25 formed between a pair of relatively adjustable brackets 176, 177, and in this slideway is mounted a vertically movable locking pin 178 adapted, when raised, to enter one of the recesses 175 and positively lock the disk 174 and the turret shaft against rotation. For operating the pin there is provided a lever 179 mounted on a stud bolt 180 (Fig. 4) and pivotally connected to the pin. Intermediate of its ends this lever carries 40 a roller 181 (Fig. 15) for engaging a cam 182 on the shaft 64. A spring 183 holds the roller in engagement with the cam and continuously exerts pressure to move the pin into operative position. This pin 178 and the coacting and operative parts may be omitted and the Geneva gear relied upon to lock the parts. It will be noted that the shaft 64 which is the main drive shaft for the Geneva gear also has three cams thereon, one (182) for locking the turret shaft, another (67) for swinging the lever 69 to operate the centering pins, and a third (154) for raising the rod 153 to operate the carrier 144.

60 The turret 163 is provided with a plurality of radially disposed blank carriers 184 (Figs. 1 and 16), each having a central stud or centering pin 184^a to enter the perforation of the blank and to center the latter in respect to the several co-operating dies

to which the blanks are presented in succession. The centering pins may be coned at their base ends to chamfer or countersink the hole in the nut. The turret has a series of face plates 185 each provided with a 70 threaded boss receiving a collet 186 and a nut 187. By tightening these nuts the blank carrying punches may be rigidly secured to the turret. For backing up each punch there is provided a head or disk portion 188 which 75 rests upon an adjustable wedge 189.

Thus each blank carrying punch may be adjusted endwise, that is, radially of the turret, and may be rigidly locked to the 80 turret.

For transferring the blanks from the strips 162 of the supply guide 159 to the centering and carrying studs of the several punches 184 of the turret, there may be provided the transfer mechanism shown particularly in Figs. 1, and 23 to 27 inclusive. Another form is shown in Figs. 30 and 31. The several punches 184 are stopped in succession with their studs in alignment with said guide 159 and the transferring takes 85 place while the parts are in this position. The main frame intermediate the supply guide and the turret is provided with a slide 190 having a dove-tail base portion mounted between relatively adjustable undercut guide members 191, 192. This slide 190 presents a rack 193 along its upper edge which meshes with a segment 194 carried by an arm 195 mounted on a rock shaft 196. The mechanism for oscillating this shaft 196 will be described hereinafter. The slide 190 has an arm 197 which carries a stud bolt 198 and rotatably mounted on this stud bolt is the blank transferring and rotating device 199. The bracket which supports the slide 190 carries a rack 200 with which engages a segmental gear 201 rigid with the transfer device. The rack is supported at opposite ends so as to leave an opening in the rear thereof along which may move the arm 197 of the slide 190. The collar 202 of the transfer device, and which has the gear segment 201 also has oppositely disposed parallel guide faces 203 for sliding engagement with the guides 204 at opposite 90 ends of the rack 200.

The transfer device 199 includes a spring clamp for holding the blanks, comprising sleeve portion 205 and upper and lower clamping flanges 206 and 207. The lower flange 207 may be rigid with the sleeve portion while the upper flange 206 is mounted for slight relative movement in respect to the lower flange. The flanges 206 and 207 need not be annular, although they are preferably of this form so that wear may be distributed by rotating them and bringing new surfaces into operation. They are preferably beveled at their outer edges to receive the nuts or blanks to be transferred. As 95

shown, the sleeve portion has an adjustable collar 208 above the upper flange 206 and provided with springs 209 for yieldingly resisting but permitting a slight vertical movement of the upper flange and normally holding it down against a shoulder on the sleeve portion.

In the operation of this transfer device, the parts are in the position shown in Figs. 24 and 25, and in solid lines in Fig. 9, at the end of the forward or working stroke of the piercing, cut-off and trimming punches which are carried by main slide. The trimming punch 24 in the final step of its operation forces a blank to the receiving end of the supply tube (Fig. 9) and the latter being full of blanks, the last blank of the series will be automatically forced to the delivery end of said tube, between the strips 162, where it is in position to be received and gripped between the upper and lower flanges 206 and 207 of the transfer device. The arm 195 and segment 194 operate the transfer device from the position shown in Figs. 24 and 25 through the position shown in dotted lines in Fig. 26 to the position shown in Fig. 27. During the first portion of this movement the collar of the transfer clamp will be held against rotation by the engagement of a guide face 203 with the guide 204. As soon as the parts reach the beginning of the rack section 200 the gear segment 201 will come into mesh with the rack and rotate the collar and transfer device through 180° until the opposite guide face 203 comes into contact with the other guide 204. During the further swinging movement of the arm 195 and the further movement of the slide 190 the transfer device will be held against rotation but will be moved in a straight line direction to force the blank endwise onto the centering pin of the carrier punch 184 of the turret. It will be noted that the face of the blank which was toward the trimming punch of the main slide is the one which is presented toward the carrier punch 184. Thus the transfer device has first a sliding movement to pull the blank out of the guide, then a rolling movement through 180° to turn the concave or punched face of the blank toward the turret and then a sliding movement to drive the blank straight onto one of the centering pins of the turret.

In connection with this transfer operation, it is to be noted that the train of nuts in the guide are more or less stuck together by the powerful pressure required to drive them through the trimming dies; also at the other end of the throw the centering studs are slightly tapered and the blank must be driven onto them with considerable force; also the rotary transfer device must make a rapid rotation through 180°; and these operations must be done at high speed. For these reasons, the grip of the clamping

flanges must be powerful in order to prevent any misplacement or displacement of the blank and the transfer device is preferably reciprocated in such a manner as to drive the clamp onto the nut blank in the supply tube at one end of the stroke and to drive the nut onto the tapered centering pin of the turret, at the other end of the stroke, by an impact blow delivered with considerable violence. Preferably this is accomplished by properly graduated hammer-like blows at both ends of the throw of the transfer device. For this reason and also because of the slightly varying differences of the throw due to varying thicknesses of the nuts, the mechanism that drives the transfer device has interposed therein double acting springs which permit impact terminations of the stroke in both directions, the tempered violence of which can be accurately regulated. A desirable arrangement of springs for this purpose will be described herein-after.

As previously pointed out, the turret has a step by step rotary movement so that the several punches 184 are presented in succession to the transfer device.

The blanks on the turret are presented to a series of trimming dies or other mechanisms for completing the nut. I do not wish to be limited to any particular number or to the specific character of the dies with which the punches on the turret cooperate. In the machine as illustrated, the first die acts to flatten the nut, the second to crown it, and the third and fourth to give the final trimming operation. Arranged around the turret are four rock shafts 210, 211, 212, and 213 (Figs. 1, 4 and 16) for operating the four mechanisms above referred to. Each rock shaft is mounted in a pair of spaced bearings in the main frame. These two bearings include conical bushings 214 and 215 (Fig. 16) mounted in corresponding conical sleeves and adjustable endwise by threaded nuts 216 and 217 which may be clamped in adjusted position to the main frame. Each rock shaft has rigidly secured thereto at the outer end an arm or lever 218 extending in a substantially radial direction in respect to the turret, and each of these lever arms is connected by a link 219 to an oscillatory or rocking disk 220 mounted on the bearing sleeve 168. Thus as the disk oscillates on its bearings on said sleeve each of the several rock shafts is caused to oscillate about its own axis.

For oscillating the disk there is provided a bar 221 connected thereto by a pin 222 and extending to the opposite end of the machine (Figs. 2, 3, 4 and 28). This bar has operative connections with the main shaft whereby it is moved back and forth once during each rotation of the main shaft. This mechanism is shown as including an

extension 223 on the lever arm 13 above the roller 12 of the latter and connected to the bar 221 by a pin 224. The bar 221 thus moves back and forth with the main slide 10 but through a somewhat greater range.

The oscillation of the disk 220 causes back and forth rocking of the rock shafts 210, 211, 212 and 213, and simultaneous operation of the several dies on the blanks which are carried by the several punches 184. Each of the four rock shafts 210, 211, 212 and 213 has an eccentric or crank portion 227 which engages with a slide 228 mounted between adjustable guide flanges 229 on the frame of the machine. Each slide carries a face plate 230 which latter is supported in a cap 231 and carries a die holder 232. The die is held in position in the holder by a nut 233. The dies which are thus operated by the rotation of the four rock shafts 210 to 213 inclusive include a flattening die 234, a crowning die 235, a first trimming die 236 and a second trimming die 237 (Fig. 1). One of these trimming dies may be omitted. These dies are spaced at equal distances apart around the turret, and come in exact alignment with the slug carriers or punches on the turret in each position of the latter. Each die holder is backed up by and is adjustable toward the turret by means of a wedge 238.

The crowning and trimming dies are forced over the nut blanks which are held stationary by the punches 184 and each of these two dies has associated therewith means for ejecting the nut to leave it in place on the centering pin when the die retreats after performing its operation. Each ejector is larger than the hole in a nut and is in the form of a rod 239 (Figs. 16 and 17) carried by a bracket 240 and disposed within a slot or chamber in the die holder and its cap. The ejector and its bracket are stationary when the die moves over the blank so that the entry of the blank into the die is not in any way interfered with by the ejector but upon the return movement of the die during the next half revolution of the main shaft the ejector forces the nut blank back out of the die leaving it on the punch 184 ready to be carried along to the next die. The end of the ejector may be positioned to just clear the path of the outer ends of the punches. The last of the four dies, that is, the one for giving the second trimming operation, is not provided with any ejector and the die holder and cap are provided with a discharge opening 241 from which the finished nuts are delivered. No ejector is needed with such dies as give merely a flattening or crowning operation. The last die 237 is a trimming die and is provided with no ejector. Consequently the nut will stick in the die opening rather than on the mandrel due to the tight fit of the die

and to the great difference in surface areas of the nut which are respectively engaged by the die and the mandrel. The next nut will force the one deposited in the die on through a chute forming a continuation of the die opening and out through the opening 41.

The transfer device may be operated from any of the various mechanisms hereinbefore described, but preferably includes yielding connections rather than rigid ones. The operating connection which may be employed for oscillating the rock shaft 196 and swinging the arm 195 with its segment, is shown in Figs. 4 and 28. This includes a lever arm 242 secured to the rock shaft 196, and upon the opposite side of the machine. The arm 242 has a slot receiving a pin 243 which carries a collar 244 slidable along a rod 245. The rod has one end pivotally connected to the oscillatory disk 220 and in such position that the rod is given a back and forth movement by oscillation of the disk. The rod 245 has stop collars 246 upon opposite ends thereof, and springs 247 between these collars and the collar 244. As the disk 220 oscillates and the rod 245 reciprocates, the arm 242 is caused to swing back and forth but the springs permit the application of yielding pressure and a cushioning at each end of the stroke and permit the arm to stop when the transfer device is at the limit of its movement. This is important as variations in the thickness of the blanks will cause variation in the position of the last blank in the supply guide from which the transfer device takes them. Also as the piercing punch wears, the holes in the blanks may become smaller, and the springs permit a hammer blow by the transfer device in driving the blank onto the centering pins of the punches 184. This mechanism is merely one form of device which may be employed for operating the transfer device from one of the other moving parts and in proper timed relationship to the other moving parts of the machine.

It will be obvious that many, if not all, of the specific details of construction may be varied without departing from the spirit of my invention or the scope thereof as defined in the appended claims. I have not attempted to indicate the various alternative constructions which may be employed in place of the specific features illustrated, but merely as examples will note two such modifications which are in some respects preferable to the forms illustrated in connection with the other features of the machine. In Fig. 29 I have shown another form which the stripper mechanism may assume. In this form there is a stripper carrying arm 30^a which instead of being suspended from an overhead pivot bar, extends upwardly from a lower pivot bar 31^a. A spring 250 acts on the stripper arm 30^a to

pull it away from the stock when said stripper arm is released by the withdrawal of the wedge bar 35. The pivot pin 31^a is mounted on an arm 251, pivoted on a rock 5 shaft or stud bolt 252. The arm is rigid with a lever 253, which may be held against an adjustable stop 254 to hold the pivot pin of the stripper arm in the desired normal position. The pivot 252 may be carried by 10 sliding block 255, which may be adjusted to bring the operating face of the stripper arm parallel to the piercing die 140 and the face of the stock.

The stripper arm at its lower end preferably carries a shield 256 which prevents small pieces of metal from getting into the bearing of the stripper arm on the pivot pin. This construction permits of a very quick and easy removal of the stripper arm when 15 it is necessary to replace the piercing die 140. By swinging the upper end of the lever 253 toward the left from the position shown in Fig. 29, the pivot pin 31^a will be lowered and the upper end of the stripper will be 20 brought to a point below the piercing die. At the same time it will relieve tension on the spring 250 and permit the disengagement of the spring if desired. The bearing of the stripper arm on the pin 31^a is preferably 25 open at the lower side so that when the spring is disengaged, the stripper arm may be entirely removed without the use of any tools and in the minimum time. Any suitable means may be employed for holding the 30 lever 253 against the stop 254 during the normal operation of the machine.

Another means which may be employed for controlling the movement of the transfer mechanism is illustrated in Figs. 30 and 40 31. It will be recalled that this mechanism has first a straight line movement to pull the blank from the end of the guide supply and to separate it from the next following blank in the guide, then a rotary movement 45 through 180° and then a straight line movement to force the slug onto the centering pin of the punch 184. Instead of using a rack and pinion as illustrated in Figs. 23 to 27 inclusive, I may employ a cam slot for the 50 same purpose. As illustrated in Figs. 30 and 31, the slide 190, which is moved back and forth by the action of the oscillatory segment arm 195, has a downwardly and outwardly extending bracket 197^a, serving 55 as a journal for a vertical shaft carrying the transferring device. Instead of having a rigid stud shaft on the bracket and upon which stud the transferring device rotates, I mount the shaft for rotation in a bearing 60 on the arm 197^a and rigidly connect the transferring device to the said shaft. The pinion 201 and the rack bar 200 are omitted, as well as the guide parts 202, 203 and 204. In place of these parts, the stud carries a 65 collar 260 below the arm 197^a and this collar

has an arm 261 provided with a depending pivot pin on which is mounted a roller 262. The bracket 191, in which the slide 190 is mounted, has an outwardly extending flange 263 provided with a cam slot 264, which receives the roller 262. The terminal portions of this slot are substantially in alignment with each other and substantially straight, while the intermediate portion curves outwardly from each end to a central position 70 which is at a distance from the line of the terminal portions substantially equal to the length of the arm 261. The operation of this construction is substantially as follows: With the parts in the position shown in 75 solid lines in Fig. 31, it will be noted that the arm 261 extends toward the left from the transferring device. As the slide which carries this transferring device moves towards the left, the roller will travel out the curved or cam slot until the slide reaches the middle position, where the arm will extend outwardly at right angles from its initial position and will be in the position indicated in dotted lines in Fig. 31. As the 80 slide continues to move toward the left, the arm 262 will trail along behind until the parts reach the position shown in dot and dash lines at the left of Fig. 31. It will be noted that by means of this simple arrangement 85 the transferring device is rotated through 180° during its movement from the supply guide to the turret punch 184, but the rotary movement begins and ends gradually so that the shock or jar incidental to 90 the sudden engagement or disengagement of the rack teeth is avoided.

As previously indicated, these two alternative constructions are merely examples of the character of substitutions or changes 105 which may be made in other parts of the machine.

It is thought that the operation of the machine will be evident from the foregoing description and that the further description 110 of the operation is unnecessary. It might be noted that the cams of the machine are so positioned and the gearing is such that a power is applied to force the dies onto the centering pins of the turret punches during 115 a return movement of the main slide and likewise the punches of the main slide operate during the outward movement of the dies which encircle the turret. Thus, the power required is distributed into different 120 parts of the cycle rather than being concentrated at a single point. Preferably the cam 5 is of such form that during 180° rotation it advances the main slide and during a 135° rotation returns it to starting 125 position. During the next 45° rotation the parts are at rest and the bar feeding mechanism is being operated. The cam which forces the dies onto the plungers 184 preferably has a very slight let-off immediately 130

after reaching final position so that the strain on the parts, and particularly the pressure on the metal in the bearings, is relieved prior to the outward movement of the dies. 5 While, as before stated, various parts of the machine and in fact the entire organization may be employed for shaping square nuts and various other articles and while even in the making of hex nuts the order and disposition of the cuts, trims and forgings may 10 be varied widely, there is peculiar advantage in the preferred method. This method is peculiarly adapted for making cold forged hex nuts from iron or mild steel bars, the thickness of which is approximately the same 15 as that of the completed nut and the width of which is approximately the same as the smaller diameter of the hexagon of the nut. As before explained, the feed mechanism 20 feeds the bar step by step exact distances substantially equal to the major diameter of the nut, positively and without the use of an end stop gauge for the bar. During the 25 operation of punching out the central slug to make the hole through the nut, the bar is rigidly held by the massive wedge backed stripper clamp 30, against the die 140 (see Fig. 14), while at the same time the top and bottom surfaces are held by similar rigid 30 clamping between the centering gauges 46 and 47 which are backed by the mass of the bars 48, 49 which carry them and which are themselves backed by the massive short arms 52, of levers 57 (see Fig. 8). These tend to 35 limit spread of the metal by the piercing punch on four sides while spread of the metal endwise of the bar is opposed by allowing one perforated blank to remain unsevered on the end of the bar between the 40 piercing punch 22 and the cut-off punch 23, while the piercing punch is piercing the next succeeding blank. (See Fig. 14). The metal intervening between the punched hole and the one being punched is the greatest possible 45 without waste because the blanks are cut point to point lengthwise of the bar so that major diameters of the hexagon intervene between hole centers, which would not be the case if the successive blanks were cut 50 with flat sides adjacent.

An important feature is that the blank when finally severed by the cut-off punch 23 has the four cut-off sides much more obtuse than those of a regular hexagon so 55 that the three trimming dies through which the blank is subsequently forced by the punch 24 take off successive triangular chips, producing the true hexagon practically without decreasing the original diameter of the blank 60 in a direction lengthwise of the bar. In this way these four surfaces which are necessarily rough from a violent punching and tearing operation of the cut-off punch 23, have their roughness worked off and worked down 65 on the torn surfaces, by taking off the suc-

cessive thin shavings on the dies 145, 146 and 147.

The blanks emerging from these dies are naturally somewhat crowned on the forward surface and concaved on the rear surfaces by the great pressure upon the train of nuts in the trimming operation, and they are rotated through 180° so that the incipient crown is available in the turret forging machine, requiring minimum refashioning to 75 produce the desired perfect crown.

Thereafter, the turret permits of perfecting the shape of the blank by end pressure in die 234, and a further perfecting of the crown and also the sides in box die 235. This 80 is followed by a light trim of the sides in die 236 and the operation is completed by a finish trim which amounts to scarcely more than a planishing of the side surfaces of the 85 nut in die 237.

In this way, I turn out a cold forged nut with perfect bottom, crown and sides, ready 90 for the threading, which is easily accomplished with a smooth finish for both ends of the thread by reason of the slight coning or chamfer which has been formed at both ends of the hole in the prior forging operations.

I claim:

1. A nut making machine, comprising a 95 suitable frame, a transverse drive shaft near one end thereof; a slide reciprocated lengthwise of the machine by said shaft; piercing, cut-off and trimming punches, arranged on said slide, and cooperating stationary dies 100 in alignment therewith; an indexing turret rotating in a vertical plane and carrying mandrel studs in alignment with the outlet of said trimming dies for receiving blanks therefrom; radially arranged, cooperating, 105 crowning and trimming dies simultaneously reciprocating to and from said mandrels when the latter are held stationary in their indexed positions.

2. A nut making machine, comprising a 110 suitable frame, a transverse drive shaft near one end thereof; a slide reciprocated lengthwise of the machine by said shaft; piercing, cut-off and trimming punches, arranged on said slide, and cooperating stationary dies 115 in alignment therewith; an indexing turret rotating in a vertical plane and carrying mandrel studs in alignment with the outlet of said trimming dies for receiving blanks therefrom; radially arranged, cooperating, 120 crowning and trimming dies simultaneously reciprocating to and from said mandrels when the latter are held stationary in their indexed positions; said turret mandrels and cooperating dies being all in the same 125 vertical longitudinal plane of the machine.

3. A nut making machine, comprising a suitable frame, a transverse drive shaft near one end thereof; a slide reciprocated lengthwise of the machine by said shaft; piercing, 130

- cut-off and trimming punches, arranged on said slide, and cooperating stationary dies in alignment therewith; an indexing turret rotating in a vertical plane and carrying mandrel studs in alignment with the outlet of said trimming dies for receiving blanks therefrom; radially arranged, cooperating crowning and trimming dies simultaneously reciprocating to and from said mandrels when the latter are held stationary in their indexed positions; said turret mandrels and cooperating dies being all in the same vertical longitudinal plane of the machine and the turret head being supported by an overhang bearing in the rear thereof and the frame having a large central opening so that all parts of the turret head and the cooperating dies are accessible from the front side of the machine.
- 10 4. A nut making machine, comprising a suitable frame, a transverse drive shaft near one end thereof; a slide reciprocated lengthwise of the machine by said shaft; piercing, cut-off and trimming punches, arranged on said slide, and cooperating stationary dies in alignment therewith; an indexing turret rotating in a vertical plane and carrying mandrel studs in alignment with the outlet of said trimming dies for receiving blanks therefrom; radially arranged, cooperating crowning and trimming dies simultaneously reciprocating to and from said mandrels when the latter are held stationary in their indexed positions; said turret mandrels and cooperating dies being all in the same vertical longitudinal plane of the machine and the turret head being supported by an overhang bearing in the rear thereof and the frame having a large central opening so that all parts of the turret head and the cooperating dies are accessible from the front of the machine and said shaft, slide, punches, stationary dies, and the axis of the turret being all horizontal.
- 15 5. A nut making machine, including horizontally reciprocating punches and stationary dies, for piercing, cutting-off and trimming nut blanks, in combination with a blank finishing mechanism of the turret type receiving blanks from the trimming dies, the axis of the turret being at right angles to and in the same horizontal plane with the trimming dies and the plane of rotation of the turret head being in the vertical longitudinal plane of the machine.
- 20 6. A nut making machine, including horizontally reciprocating punches and stationary dies, for piercing, cutting-off and trimming nut blanks, in combination with a finishing mechanism of the turret type receiving blanks from the trimming dies, the axis of the turret being at right angles to and in the same horizontal plane with the trimming dies and the plane of rotation of the turret head being in the vertical longitudinal plane of the machine; said punches and stationary dies and turret finishing mechanism being all exposed and accessible from the front side of the machine; together with driving connections for all said mechanisms and means for feeding bar stock to the punches, all located in and accessible from the rear side of the machine.
- 25 7. A nut making machine, comprising a frame having a drive shaft near one end; a turret shaft parallel therewith near the other end of the machine mounted in bearings at the back side of the machine and provided with a blank carrying turret overhung toward the front side of the machine, bar clamping, piercing and cutting-off devices between said shafts, directly accessible on the front side of the machine; and transfer devices for receiving the pierced blanks and transferring them to the turret; said transfer device and said turret being also directly accessible on the front side of the machine.
- 30 8. A nut making machine, comprising bar feeding, piercing, cutting-off and trimming mechanism, in combination with crowning and finishing mechanism, including an indexing turret rotated in a vertical longitudinal plane of the machine, and transfer mechanism between said first mechanism and said turret mechanism, the work engaging parts of the piercing, cutting-off, transfer and turret mechanisms being all exposed toward and accessible from the front side of the machine; and the driving connections therefor, as also the feed mechanism, being located on the rear side of the machine and accessible therefrom.
- 35 9. A nut making machine, comprising bar feeding mechanism; blank forming mechanism including a plurality of reciprocating punches; adjacent blank shaping mechanism including a turret and a plurality of mechanisms for further shaping the blank and intermediate carrier mechanism for positively transferring the blanks from the punch mechanism directly to the adjacent turret mechanism, in combination with a single drive shaft for operating all said mechanisms and intermediate motion transmitting device timed so that said punch mechanism and said turret shaping mechanism execute their metal working strokes non-simultaneously.
- 40 10. A nut making machine, comprising a frame, a transverse drive shaft near one end thereof and a turret shaft with indexing mechanism near the other end thereof, mounted in an overhang bearing parallel with the drive shaft and carrying an overhung turret head provided with radial studs accessible from the front side of the machine; a reciprocating slide between the drive shaft and the turret head, carrying piercing, cut-off and trimming punches;
- 45 50 55 60 65 70 75 80 85 90 95 100 105 110 115 120 125 130

means for feeding bar stock transversely of the machine in the path of reciprocation of said punches, cooperating stationary dies in operative relation to said punches; and a 5 transfer mechanism for receiving blanks from the trimming dies, rotating them through 180° and forcing them onto successively presented studs on the turret.

11. A metal working machine having a 10 multiplicity of reciprocating metal working devices by which a multiplicity of operations are performed on a plurality of the blanks simultaneously and on all blanks successively, including a reciprocating slide 15 carrying a plurality of blank forming devices for shaping and severing blanks from bar stock; a turret metal shaping mechanism including a plurality of blank holders and a cooperating plurality of metal shaping 20 devices; and intermediate means for transferring means for picking up the blanks from the blank forming devices and jamming them on to the turret devices, in combination with a drive shaft and intermediate 25 power transmitting mechanism whereby each revolution of the drive shaft operates all of the metal working devices once but the slide devices and the turret devices have their operative strokes during different parts 30 of each revolution.

12. A machine for performing a multiplicity of operations on a succession of blanks, including a mechanism in which the preliminary blank forming operations are 35 performed simultaneously on a plurality of the successive blanks, another closely adjacent mechanism to which said blanks are transferred positively and successively and in which a plurality of finishing operations 40 are further performed simultaneously on said blanks successively, in combination with a single drive shaft and an intervening power transmitting means timed so that every operation is performed during every 45 revolution of the drive shaft but the work strokes in the first mechanism are non-simultaneous with the work strokes of the finishing mechanism.

13. A machine for making nuts comprising 50 a multiplicity of reciprocating devices performing punching operations and finishing operations on a succession of blanks, in combination with a single drive shaft and connections whereby said shaft forces the 55 working strokes of said reciprocating punches during part of each revolution and the working strokes of said finishing devices during another part of the same revolution, all of said punch devices being operated by a 60 single reciprocating sliding, a mandrel turret for carrying and holding blanks in operative relation to the successive finishing devices, said finishing devices being radially operated relative to the turret, automatic 65 indexing mechanism associated with the tur-

ret for properly aligning the holding mechanism with the finishing devices.

14. A machine for making nuts comprising 70 a multiplicity of reciprocating devices performing punching operations and finishing operations on a succession of blanks, in combination with a single drive shaft and connections whereby said shaft forces the working strokes of said reciprocating punches during part of each revolution and 75 the working strokes of said finishing devices during another part of the same revolution, all of said punch devices being operated by a single reciprocating slide; a turret with which said finishing devices co-operate, the turret including radial studs that carry and present the perforated blanks to the shaping devices.

15. A machine of the class described, including longitudinally extending front and 80 rear frame members; a transverse horizontal drive shaft mounted near one end thereof; horizontal, parallel piercing, cut-off and trim punches reciprocated lengthwise of the machine by each revolution of the drive 90 shaft; feed mechanism on the rear of the machine feeding bar material from rear to front across the path of the punches, co-operating stationary dies in the rear of the punches through the last of which dies the 95

blanks are crowded in a continuous train by the punch lengthwise of the machine and near the front thereof; a turret shaft having its axis parallel with the drive shaft and with the line of feed of the bar material, 100 supported in bearings located at the rear of the machine, an indexing turret head carried by the overhung end of said shaft near the front of the machine, in the vertical plane of said train of nut blanks, and provided with radial stud mandrels, successively indexed to alignment with said train of blanks; a series of radially reciprocating dies each adapted to register with one of the indexed positions of the turret mandrels 105 and means for reciprocating the dies and the transfer mechanism simultaneously while the turret is in each of its indexed positions; reciprocating means near the front of the machine for transferring said blanks 110 one at a time from the punch mechanism to the successive turret mandrels; whereby all devices for operating on the several blanks are adjacent the front of the machine; and the front frame member being provided with 115 openings through which said devices are all accessible.

16. The combination specified by claim 15, with the further feature that the turret rotates upward from the transfer mechanism 120 to indexed position in operative relation to the first reciprocating die and said die is a face die which in its operation drives the nut blank more firmly on the stud of the 125 turret mandrel.

17. A machine of the class described, including longitudinally extending front and rear frame members; a transverse horizontal drive shaft mounted near one end thereof; 5 horizontal, parallel piercing, cut-off and trim punches reciprocated lengthwise of the machine by each revolution of the drive shaft; feed mechanism on the rear of the machine feeding bar material from rear to 10 front across the path of the punches; co-operating stationary dies in the rear of the punches through the last of which dies the blanks are crowded in a continuous train by the punch lengthwise of the machine and 15 near the front thereof; a turret shaft having its axis parallel with the drive shaft and with the line of feed of the bar material, supported in bearings located at the rear of the machine, an indexing turret head carried by the overhung end of said shaft near 20 the front of the machine, in the vertical plane of said train of nut blanks, and provided with radial stud mandrels, successively indexed to alignment with said train of 25 blanks; a series of radially reciprocating dies each adapted to register with one of the indexed positions of the turret mandrels and means for reciprocating the dies and the transfer mechanism simultaneously while 30 the turret is in each of its indexed positions; reciprocating means near the front of the machine for transferring said blanks one at a time from the punch mechanism to the successive turret mandrels; whereby all 35 devices for operating on the several blanks are adjacent the front of the machine; and the front frame member being provided with openings through which said devices are all accessible, the first reciprocating die 40 being a face die which in its operation drives the nut blank more firmly on the stud of the turret mandrel and the last reciprocating die being a finishing die which engages the sides of the blank and strips the 45 same from the stud mandrel.

18. The combination specified by claim 17, with the further feature that a reciprocating die intermediate the first die and the last die of the turret mechanism is a box die 50 having a stationary central ejector whereby the blank is stripped from the box die and remains on the mandrel stud until stripped therefrom by the finishing die.

19. In a metal working machine of the 55 class described, blank forming and severing mechanism including reciprocating punches and stationary dies; and blank finishing mechanism including reciprocatory die shaping devices, through both of 60 which mechanisms the severed blanks are fed step by step in combination with a feed mechanism for feeding bar stock intermittently, step by step, across the path of forming punches, including a step by step actuating element and a reciprocatory con-

trolling mechanism therefor positively actuated for the stroke in one direction and spring actuated for the return stroke; together with means for throwing out the feed mechanism without stopping the other 70 mechanisms, said means including a detent arranged to be interposed at the end of a positive stroke to prevent the spring from effecting the return stroke.

20. In a metal working machine of the 75 class described, a blank forming and severing mechanism including parallel piercing and cut-off punches arranged to operate successively on the same blanks, in combination with a feed mechanism for feeding bar 80 stock, intermittently step by step, across the paths of the piercing and cut-off punches, one element of the feed mechanism being positively actuated to cause the feeding stroke and actuated non-positively to cause 85 the return stroke; together with means for throwing out the feed mechanism at the end of a feeding stroke without stopping the other mechanism, said means including a positive detent arranged to be interposed 90 at the end of a positive feed stroke to prevent said non-positive return means from effecting the return stroke.

21. In a metal working machine of the 95 class described, a blank forming and severing mechanism, including parallel piercing and cut-off punches arranged to operate successively on the same blanks, in combination with a feed mechanism for feeding bar stock, intermittently, step by step, 100 across the paths of the piercing and cut-off punches, one of the elements of the feed mechanism including a spring element whereby the stroke in one direction is non-positive; and a positive detent arranged to be interposed before the beginning of the 105 non-positive stroke to prevent the spring from effecting the said stroke.

22. In a metal working machine of the 110 class described, a blank forming and severing mechanism, including parallel piercing and cut-off punches arranged to operate successively on the same blanks, in combination with a feed mechanism for feeding bar stock, intermittently, step by step, 115 across the paths of the piercing and cut-off punches, the strokes of the step by step mechanism being actuated positively in one direction and non-positively in the opposite direction; and a positive detent interposable only at the end of a positive feed stroke to prevent the non-positive actuating means 120 from effecting the stroke in the opposite direction.

23. A machine of the class described, including a piercing punch and die and a cut-off punch and die parallel with each other and spaced apart a distance equal to two 125 blanks to be cut thereby; and a drive shaft operating to reciprocate said punches: and 130

feed mechanism synchronized with the punches to feed bar material in the same plane with and across the paths of both punches, intermittently, step by step, each 5 step equal to the length of a single blank to be cut off therefrom; in combination with means for preventing distortion of the bar material by the piercing punch, said means including centering clamps engaging oppo- 10 site edges of the bar along the portion to be perforated and a stripper clamp pro- vided with a perforation through which the piercing punch operates and a clamping face for clamping the bar against the pierc- 15 ing die, together with spring actuated low pitch wedging means for clamping and rigidly locking said centering clamps and said stripper clamp.

and driving it thereon, the throw of the ac- 65 tuating mechanism being greater than the distance between the blank train and the stud but including a spring permitting stop- 70 ping of the clamp by impact on the blank, at one end of the throw, and by driving fit of the blank on the stud, at the other end of the throw.

27. In a machine of the class described, mechanism for supplying perforated nut blanks including a trimming die; a guide 75 therefrom, the outlet end of which holds the blanks with opposite sides exposed; and a punch driving through the die and guide a train of the perforated nut blanks; and blank shaping mechanism including an in- 80 dexing turret having a plurality of carrier studs each having a slightly coned projec-

24. A machine of the class described, including a piercing punch and die, in combination with means for preventing distortion of the bar material by the piercing punch, said means including centering clamps engaging opposite edges of the bar along the portion to be perforated and a stripper clamp provided with a perforation through which the piercing punch operates and a clamping face for clamping the bar against the piercing die, together with spring actuated low pitch wedging means for clamping and rigidly locking said centering clamps and said stripper clamp.

55 26. In a machine of the class described, mechanism for supplying perforated blanks including a trimming die, and a punch driving through the die a train of perforated blanks; and blank shaping mechanism including a carrier stud having a slightly coned projection adapted for driving fit with the perforations of the blanks, in combination with transfer mechanism including a carrier clamp and actuating means for driving said clamp into gripping engagement with the end blank of the train, moving said blank into alignment with the stud
60 drive said clamp into gripping engagement with a blank on the end of said guide, withdrawing it, rotating said clamp 180° into alignment with one of the studs and driving the blank onto the stud, the means for rotating the clamp including a projection on the clamp and a cooperating stationary member in the path of such projection when the slide reciprocates; and the actuating mechanism for the slide having an interposed double acting spring permitting yield in response to impacts on the rotary clamp mechanism. 120 125

29. In a machine of the class described, mechanism for supplying perforated nut blanks including a trimming die; a guide therefrom, the outlet end of which holds the blanks with opposite sides exposed; and a punch driving through the die and guide a train of the perforated nut blanks; and blank shaping mechanism including an indexing turret having a plurality of carrier studs each having a slightly coned projection adapted for driving fit with the perforations of the blanks; and means for indexing said projections successively into alignment with said train of blanks, in combination with transfer mechanism including a reciprocating slide and a rotary carrier clamp and means for actuating said slide to drive said clamp into gripping engagement with a blank on the end of said guide, with-
drawing it, rotating said clamp 180° into alignment with one of the studs and driving the blank onto the stud, the means for controlling the rotation and alignment of the clamp including two straight guide surfaces 180° apart on the clamp and a projection midway between them, and cooperating therewith a stationary guide bar having straight aligned surfaces near each end of the throw, engaging said straight guide surfaces on the clamp and intermediate detent means for engaging said projection on the clamp, the aligning surfaces on the clamp being arranged to rotate out of engagement with the cooperating stationary surfaces at the beginning and end respectively of rotation of the clamp by the projection.
30. In a nut making machine, a slide and means for reciprocating it; piercing and cut-off punches, arranged on said slide; means for feeding bar material transversely of the punches; an indexing turret rotating in a vertical plane and carrying mandrel studs in alignment with the cut-off blanks; and radially arranged means for transferring the blanks to the studs and crowning and trimming dies, all simultaneously reciprocating to and from said mandrels when the latter are held stationary in their indexed positions.
31. In a nut making machine, a slide and means for reciprocating it; piercing, cut-off and trimming punches, arranged on said slide, and cooperating stationary dies in alignment therewith; means for feeding bar material in the path of said punches; an indexing turret rotating in a vertical plane and carrying mandrel studs in alignment with the outlet of said trimming dies for receiving blanks therefrom; radially arranged transfer means and crowning and trimming dies simultaneously reciprocating to and from said mandrels when the latter are held stationary in their indexed positions; said transfer means, turret mandrels and cooperating dies all operating in the same vertical longitudinal plane of the machine.
32. In a nut making machine, a slide and means for reciprocating it; piercing, cut-off and trimming punches, arranged on said slide, and cooperating stationary dies in alignment therewith; means for feeding bar material in the path of said punches; an indexing turret rotating in a vertical plane and carrying the mandrel studs in alignment with the outlet of said trimming dies for receiving blanks therefrom; radially arranged transfer means and crowning and trimming dies simultaneously reciprocating to and from said mandrels when the latter are held stationary in their indexed positions; said transfer means, turret mandrels and cooperating dies all operating in the same vertical longitudinal plane of the machine, and said slide, and said punches reciprocating at right angles to the axis of said turret.
33. In a nut making machine, a transverse drive shaft, a slide reciprocated lengthwise of the machine by said shaft; piercing, cut-off and trimming punches, arranged on said slide; and cooperating stationary dies in alignment therewith; an indexing turret carrying mandrel studs in alignment with the outlet of said trimming dies for receiving therefrom; radially operating transfer means and crowning and trimming dies simultaneously reciprocating to and from said mandrels when the latter are held stationary in their indexed positions.
34. A machine of the class described, including horizontal, parallel, piercing, cut-off and trim punches and means for reciprocating them; mechanism for feeding bar material across the path of the punches; cooperating stationary dies in the rear of the punches through the last of which dies the blanks are crowded in a continuous train by the punch; an indexing turret head provided with radial mandrels, successively indexed to alignment with said train of blanks; a series of radially reciprocating dies each adapted to register with one of the indexed positions of the turret mandrels and means for reciprocating the dies and the transfer mechanism while the turret is in each of its indexed positions; and reciprocating means for transferring said blanks one at a time from the punch mechanism to the successive turret mandrels, the first reciprocating die being a face die which in its operation drives the nut blank more firmly on the stud of the turret mandrel and the last reciprocating die being a finishing die which engages the sides of the blank and strips the same from the stud mandrel.
35. A nut making machine, comprising bar feeding, piercing and cutting-off mechanism, in combination with radially operat-

ing crowning and finishing mechanism, including an indexing turret rotating in a vertical plane adjacent and parallel with the front side of the machine and presenting the 5 blanks radially to said crowning and finishing mechanism; and transfer mechanism between said first mechanism and said turret mechanism, the work engaging parts of the punch, cut-off, transfer and turret mechanism being all exposed toward and accessible 10 from the front side of the machine; and the driving connections therefor, as also the feed and turret indexing mechanism, being located on the rear side of the machine and 15 accessible therefrom.

36. A nut making machine, comprising a frame, a transverse drive shaft and a turret shaft with indexing mechanism and a turret head provided with radial studs; a reciprocating slide between the drive shaft and the 20 turret head, carrying piercing and cut-off punches; means for feeding bar stock transversely of the machine in the path of reciprocation of said punches, cooperating stationary dies in operative relation to said 25 punches; and a transfer mechanism for receiving blanks from the punch mechanism, rotating them through 180° and delivering them upon the successively presented studs 30 on the turret.

37. A machine of the class described, including horizontal, parallel, piercing, cut-off and trim punches and means for reciprocating them; mechanism for feeding bar 35 material across the path of the punches; cooperating stationary dies in the rear of the punches through the last of which dies the blanks are crowded in a continuous train by the punch; an indexing turret head provided with radial mandrels, successively indexed to alignment with said train of 40 blanks; a series of radially reciprocating dies each adapted to register with one of the indexed positions of the turret mandrels and 45 means for reciprocating the dies and the transfer mechanism while the turret is in each of its indexed positions; and reciprocating means for transferring said blanks one at a time from the punch mechanism to 50 the successive turret mandrels.

38. The combination specified by claim 37 with the further feature that the turret rotates upward from the transfer mechanism to indexed position in operative relation to 55 the first reciprocating die and said die is a face die which in its operation drives the nut blank more firmly on the turret mandrel.

39. The combination specified by claim 37 with the further feature that the last reciprocating die is a finishing die which engages 60 the sides of the blank and strips the same from the stud mandrel.

40. The combination specified by claim 37 with the further feature that a reciprocating 65 die intermediate the first die and the last

die of the turret mechanism is a box die having a stationary central ejector whereby the blank is stripped from the box die and remains on the mandrel stud until stripped therefrom by the finishing die.

70

41. In a metal working machine of the class described, blank forming and severing mechanism including reciprocating punches and stationary dies; in combination with a feed mechanism for feeding bar stock intermittently, including feed rolls, a reciprocating actuating element and intermittent lock and release mechanism whereby the rolls rotate in one direction only, the reciprocatory actuating element of the lock mechanism being positively actuated in one direction and spring actuated in the other direction; together with means including a detent arranged to be interposed at the end of a positively actuated movement to prevent the 85 spring from effecting a return movement.

89

42. In a metal working machine of the class described, a feed mechanism for feeding bar stock, intermittently, step by step, in one direction only, including feed rolls, a reciprocatory actuating element and intermediate lock and release mechanism whereby the rolls rotate in one direction only, said actuating element being positively actuated on the feeding stroke and actuated non- 95 positively on the return stroke; and means arranged to be interposed at the end of a feed stroke to prevent said non-positive return stroke.

95

43. In a metal working machine of the class described, a feed mechanism for feeding bar stock, intermittently, step by step, in one direction, one of the actuating elements of the feed mechanism including a spring element whereby the stroke in one 100 direction is non-positive; and a positive detent arranged to be interposed before the beginning of the non-positive stroke to prevent the spring from effecting the return stroke.

110

44. In a metal working machine of the class described, a feed mechanism for feeding bar stock, intermittently, step by step, in one direction the strokes of the step by step mechanism being operated positively in one 105 direction and non-positively in the opposite direction; and a positive detent interposable only at the end of a positive feed stroke to prevent the non-positive actuating means from effecting the stroke in the opposite direction.

115

45. In a machine for making pierced blanks from bar stock, a piercing punch and die, and a cut-off device spaced apart approximately the length of two blanks to be 120 cut thereby; means for reciprocating said devices; and feed mechanism synchronized with the punches to feed bar material in the same plane with and across the paths of both punches, intermittently, step by 125 130

- step, each step equal to the length of a single blank to be cut off therefrom; in combination with means for preventing distortion of the bar material by the piercing punch, 5 said means including centering clamps engaging opposite edges of the bar along the portion to be perforated, and spring actuated low pitch wedging means for clamping and rigidly locking said centering clamps.
- 10 46. In a machine for making pierced blanks from bar stock, a piercing punch and die, in combination with means for preventing distortion of the bar material by the piercing punch, said means including 15 centering clamps engaging opposite edges of the bar along the portion to be perforated and a stripper clamp provided with a perforation through which the piercing punch operates and a clamping face for clamping 20 the bar against the piercing die, together with non-positive low pitch wedging means for clamping and rigidly locking said stripper clamp.
- 25 47. In a machine for making pierced blanks from bar stock, a piercing punch and die, in combination with means for preventing distortion of the bar material by the piercing punch, said means including centering clamps engaging opposite edges of the 30 bar along the portion to be perforated and a stripper clamp provided with a perforation through which the piercing punch operates and a clamping face for clamping the bar against the piercing die, together with 35 non-positive low pitch wedging means for clamping and rigidly locking said stripper clamp and short work arm, long-power arm lever means for locking the centering clamps.
- 40 48. In a machine for making pierced blanks from bar stock, a piercing punch and die, in combination with means for preventing distortion of the bar material by the piercing punch, said means including centering clamps engaging opposite edges of the 45 bar along the portion to be perforated and a stripper clamp provided with a perforation through which the piercing punch operates and a clamping face for clamping the bar against the piercing die, together with 50 spring actuated low pitch wedging means for clamping and rigidly locking said stripper clamp.
- 55 49. In a machine of the class described, mechanism for supplying perforated blanks including a trimming die, and a punch driving through the die a train of perforated blanks; and blank shaping mechanism including a carrier stud adapted to engage the 60 perforations of the blanks, in combination with transfer mechanism including a carrier 65 clamp and actuating means for driving said clamp into gripping engagement with the end blank of the train, moving said blank into engagement with the stud, the throw of the actuating mechanism being greater

than the distance between the blank train and the stud but including a spring permitting stopping of the clamp by impact on the train of blanks and of the blank on the stud.

50. In a machine of the class described, mechanism for supplying a train of perforated blanks; and blank shaping mechanism including a carrier mandrel adapted to receive the blanks, in combination with transfer mechanism including blank engaging 70 means and actuating means for driving the latter into engagement with the end blank of the train, and moving said blank into engagement with the mandrel, the throw of the actuating mechanism being greater than 75 the distance between the blank train and the stud but including a spring permitting stopping of the transfer device by impact on the blank, at one end of the throw, and by impact on the mandrel, at the other end of 80 the throw.

51. In a machine of the class described, mechanism for supplying perforated nut blanks including a guide, the outlet end of 90 which holds the blanks with opposite sides exposed; and blank shaping mechanism including an indexing turret having a plurality of carrier mandrels; and means for indexing said mandrels successively into alignment with said train of blanks, in combination with transfer mechanism including a reciprocating slide and a rotary carrier clamp and means for actuating said slide to drive said clamp into gripping engagement with a blank in the end of said guide, withdrawing it, rotating said clamp 180° into alignment with one of the studs and driving the blank onto the stud, the means for rotating the clamp including a projection on 95 the clamp and a cooperating stationary member in the path of such projection when the slide reciprocates.

52. In a machine of the class described, mechanism for supplying perforated nut blanks including a guide the outlet end of 110 which holds the blanks with opposite sides exposed and means driving through the guide a train of the perforated nut blanks; and blank shaping mechanism including an indexing turret having a plurality of carrier studs adapted for driving fit with the perforations of the blanks; and means for indexing said projections successively into alignment with said train of blanks, in combination with transfer mechanism including a reciprocating slide and a rotary carrier clamp and means for actuating said slide to drive said clamp into gripping engagement with a blank on the end of said guide, withdrawing it, rotating said clamp 180° into alignment with one of the studs and driving the blank onto the stud, the means for rotating the clamp including a projection on 115 the clamp and a cooperating stationary member in the path of such projection when the slide reciprocates.

120 53. In a machine of the class described, mechanism for supplying perforated nut blanks including a guide the outlet end of which holds the blanks with opposite sides exposed and means driving through the guide a train of the perforated nut blanks; and blank shaping mechanism including an indexing turret having a plurality of carrier studs adapted for driving fit with the perforations of the blanks; and means for indexing said projections successively into alignment with said train of blanks, in combination with transfer mechanism including a reciprocating slide and a rotary carrier clamp and means for actuating said slide to drive said clamp into gripping engagement with a blank on the end of said guide, withdrawing it, rotating said clamp 180° into alignment with one of the studs and driving the blank onto the stud, the means for rotating the clamp including a projection on the clamp and a cooperating stationary member in the path of such projection when the slide reciprocates.

125 54. In a machine of the class described, mechanism for supplying perforated nut blanks including a guide the outlet end of which holds the blanks with opposite sides exposed and means driving through the guide a train of the perforated nut blanks; and blank shaping mechanism including an indexing turret having a plurality of carrier studs adapted for driving fit with the perforations of the blanks; and means for indexing said projections successively into alignment with said train of blanks, in combination with transfer mechanism including a reciprocating slide and a rotary carrier clamp and means for actuating said slide to drive said clamp into gripping engagement with a blank on the end of said guide, withdrawing it, rotating said clamp 180° into alignment with one of the studs and driving the blank onto the stud, the means for rotating the clamp including a projection on the clamp and a cooperating stationary member in the path of such projection when the slide reciprocates.

130 55. In a machine of the class described, mechanism for supplying perforated nut blanks including a guide the outlet end of which holds the blanks with opposite sides exposed and means driving through the guide a train of the perforated nut blanks; and blank shaping mechanism including an indexing turret having a plurality of carrier studs adapted for driving fit with the perforations of the blanks; and means for indexing said projections successively into alignment with said train of blanks, in combination with transfer mechanism including a reciprocating slide and a rotary carrier clamp and means for actuating said slide to drive said clamp into gripping engagement with a blank on the end of said guide, withdrawing it, rotating said clamp 180° into alignment with one of the studs and driving the blank onto the stud, the means for rotating the clamp including a projection on the clamp and a cooperating stationary member in the path of such projection when the slide reciprocates.

tion when the slide reciprocates; and the actuating mechanism for the slide having an interposed double acting spring permitting yield in response to impacts on the rotary clamp mechanism.

53. In a machine of the class described, mechanism for supplying perforated nut blanks including a guide the outlet end of which holds the blanks with portions laterally exposed; and means supplying through the guide a train of the perforated nut blanks; and blank shaping mechanism including a carrier adapted to be moved into alignment with said blanks; in combination with transfer mechanism including a reciprocating slide and a rotary carrier clamp and means for actuating said slide to drive said clamp into gripping engagement with a blank in the end of said guide, withdrawing it, rotating said clamp 180° into alignment with said carrier and driving the blank into engagement therewith, the means for controlling the rotation and alignment of the clamp including two straight guide surfaces 180° apart on the clamp and a projection midway between them, and cooperating therewith a stationary guide bar having straight aligned surfaces near each end of the throw, engaging said straight guide.

54. In a metal working machine of the class described, a feed mechanism for feeding bar stock intermittently, including feed rolls, reciprocatory actuating means and reciprocatory lock and release mechanism positively actuated in one direction and spring actuated in the other direction; together with means including a detent arranged to be interposed near the end of a positively actuated movement to prevent the spring from effecting a return movement, and interlocking under the tension of the spring so that it cannot release until near the end of a subsequent positive stroke of the reciprocatory lock and release means.

55. In a metal working machine of the class described, a feed mechanism for feeding bar stock, intermittently, step by step, in one direction only, including feed rolls, reciprocatory actuating means including an intermediate non-slip friction clutch and reciprocatory clutch controlling mechanism therefor non-positively actuated to cause engagement of the clutch on the feeding stroke; and actuated positively to release the clutch on the return stroke; and means arranged to be interposed near the end of a releasing stroke to prevent reengagement of the clutch by preventing said non-positive return stroke of the clutch controlling mechanism.

56. In a metal working machine of the class described, a feed mechanism for feeding bar stock, intermittently, step by step, in one direction only, including feed rolls, reciprocatory actuating means including an

intermediate non-slip friction clutch and reciprocatory clutch controlling mechanism therefor non-positively actuated to cause engagement of the clutch on the feeding stroke; and actuated positively to release the clutch on the return stroke; and means arranged to be interposed near the end of a releasing stroke to prevent reengagement of the clutch by preventing said non-positive return stroke of the clutch controlling mechanism, said interposed means interlocking automatically under the non-positive return effort of the clutch-controlling means so that it cannot release until relieved by a subsequent positive thrust upon the clutch controlling mechanism.

57. In a metal working machine of the class described, a feed mechanism for feeding bar stock, intermittently, step by step, in one direction, including feed rolls and reciprocatory actuating means, a cam causing the reciprocatory movement and having a dwell at both ends of the throw; a non-slip friction clutch through which the reciprocatory movement is applied to the rolls, and means for engaging said clutch during the dwell at one end of the throw and disengaging it during the dwell at the other end of the throw.

58. In a metal working machine of the class described, a feed mechanism for feeding bar stock, intermittently, step by step, in one direction including feed rolls and reciprocatory actuating means, a cam causing the reciprocatory movement and having a dwell at both ends of the throw; a non-slip friction clutch through which the reciprocatory movement is applied to the rolls, and means for engaging said clutch during the dwell at one end of the throw and releasing it during the dwell at the other end of the throw, together with means for preventing over-feed by the rolls when released, including a brake and means for tightening it near the end of the feed stroke.

59. In a metal working machine of the class described, a feed mechanism for feeding bar stock, intermittently, step by step, in one direction, including feed rolls and reciprocatory actuating means, a cam causing the reciprocatory movement and having a dwell at both ends of the throw; a non-slip friction clutch through which the reciprocatory movement is applied to the rolls, and means for engaging said clutch during the dwell at one end of the throw and disengaging it during the dwell at the other end of the throw, together with means for preventing over-feed by the rolls when released, including a brake and means for tightening it near the end of the feed stroke, said means including the same cam that controls engagement and release of the friction clutch.

60. In a metal working machine of the class described, a feed mechanism for feed-

ing bar stock, intermittently, step by step, in one direction, including feed rolls and reciprocatory actuating means, including an actuator causing the reciprocatory movement to have a dwell at both ends of the throw, a non-slip friction clutch through which the actuator applies the reciprocatory movement to the rolls, and means for engaging and disengaging said clutch during the dwells at the respective ends of the throw.

61. In a metal working machine of the class described, a feed mechanism for feeding bar stock, intermittently, step by step, in one direction, including feed rolls and reciprocatory actuating means, including an actuator causing the reciprocatory movement to have a dwell at both ends of the throw, a non-slip friction clutch through which the actuator applies the reciprocatory movement to the rolls, and means for engaging and disengaging said clutch during the dwells at the respective ends of the throw; and a friction applying means operating to prevent over-feed by the rolls at the end of the feed stroke of the actuator.

62. In a metal working machine of the class described, a feed mechanism for feeding bar stock, intermittently, step by step, in one direction, including feed rolls and reciprocatory actuating means, including a friction clutch and a clutch controlling means each including a reciprocatory member and a rotary cam for reciprocating it, each said cam having a dwell at both ends of the throw of the reciprocatory member and each having a cooperating spring element whereby the stroke in one direction is non-positive, but said cams having a predetermined difference of phase so that the clutch controlling means operates for engaging said clutch during the dwell at one end of the throw of the reciprocatory clutch member and disengaging it during the dwell at the other end of the throw.

63. In a metal working machine of the class described, a feed mechanism for feeding bar stock, intermittently, step by step, in one direction, including feed rolls and reciprocatory actuating means, including a friction clutch and a clutch controlling means each including a reciprocatory member and a rotary cam for reciprocating it, each said cam having a dwell at both ends of the throw of the reciprocatory member and each having a cooperating spring element whereby the stroke in one direction is non-positive, but said cams having a predetermined difference of phase so that the clutch controlling means operates for engaging said clutch during the dwell at one end of the throw of the reciprocatory clutch member and disengaging it during the dwell at the other end of the throw, in combination with a stop adapted to be interposed to prevent one of the spring elements from causing

the non-positive stroke of the reciprocatory member.

64. In a metal working machine of the class described, a feed mechanism for feeding bar stock, intermittently, step by step, in one direction, including feed rolls and reciprocatory actuating means, including a friction clutch and a clutch controlling means each including a reciprocatory member and a rotary cam for reciprocating it, each said cam having a dwell at both ends of the throw of the reciprocatory member and each having a cooperating spring element whereby the stroke in one direction is non-positive, but said cams having a predetermined difference of phase so that the clutch controlling means operates for engaging said clutch during the dwell at one end of the throw of the reciprocatory clutch member and disengaging it during the dwell at the other end of the throw, in combination with a stop adapted to be interposed to prevent the spring element of the clutch controlling reciprocatory member from causing the non-positive stroke of its reciprocatory member.

65. In a metal working machine of the class described, a feed mechanism for feeding bar stock, intermittently, step by step, in one direction, including feed rolls and reciprocatory actuating means, including a friction clutch and a clutch controlling means each having a reciprocatory member and the means for reciprocating one of said reciprocatory members, including a rotary cam having a dwell at both ends of the throw, and a spring element whereby the return stroke is non-positive so that said clutch controlling means operates on a non-positive stroke for engaging said clutch during the dwell at one end of the throw of the reciprocatory clutch element and for disengaging it during the dwell at the other end of the throw.

66. In a metal working machine of the class described, a feed mechanism for feeding bar stock, intermittently, step by step, in one direction, including feed rolls and reciprocatory actuating means, including a friction clutch and a clutch controlling means each having a reciprocatory member and the means for reciprocating one of said reciprocatory members, including a rotary cam having a dwell at both ends of the throw, and a spring element whereby the return stroke is non-positive so that said clutch controlling means operates on a non-positive stroke for engaging said clutch during the dwell at one end of the throw of the reciprocatory clutch element and for disengaging it during the dwell at the other end of the throw, in combination with a stop adapted to be interposed to prevent one of the spring elements from causing the non-positive stroke of its reciprocatory member.

67. In a metal working machine of the class described, a feed mechanism for feeding bar stock, intermittently, step by step, in one direction, including feed rolls and reciprocating actuating means, including a friction clutch and a clutch controlling means each having a reciprocating member and the means for reciprocating one of said reciprocating members, including a rotary cam having a dwell at both ends of the throw, and a spring element whereby the return stroke is non-positive so that said clutch controlling means operates on a non-positive stroke for engaging said clutch during the dwell at one end of the throw of the reciprocating clutch element and for disengaging it during the dwell at the other end of the throw, in combination with a stop adapted to be interposed to prevent the spring element of the clutch controlling reciprocating member from causing the non-positive stroke of its reciprocating member.
68. A feed roll and means for intermittently rotating it, including a shaft and a friction clutch including a driven member rigid with the shaft, a driving member freely movable longitudinally and circumferentially of the shaft, a third clutch member splined to the shaft and longitudinally movable into friction engagement with said driving member and to force the latter into friction engagement with said fixed member; means, including relatively fixed and movable screw elements for forcing the clutch members into locking engagement, in combination with means for reciprocating said driving clutch member about said shaft with a dwell at both ends of each stroke and means for relatively rotating the screw elements to engage and disengage the clutch members when the driving member is stationary at the respective ends of the stroke.
69. A feed roll and means for intermittently rotating it, including a shaft and a friction clutch including a driven member rigid with the shaft, a driving member freely movable longitudinally and circumferentially of the shaft, a third clutch member splined to the shaft and longitudinally movable into friction engagement with said driving member and to force the latter into friction engagement with said fixed member; means, including relatively fixed and movable screw elements for forcing the clutch members into locking engagement, in combination with means for reciprocating said driving clutch member about said shaft with a dwell at both ends of each stroke and means for relatively rotating the screw elements to engage and disengage the clutch members when the driving member is stationary at the respective ends of the stroke.
70. A feed roll and means for intermittently rotating it, including a shaft and a friction clutch including a driven member rigid with the shaft, a driving member freely movable longitudinally and circumferentially of the shaft and relatively movable members for forcing said driving member into non-slip engagement with said fixed member on the shaft, in combination with means for forcing continuous reciprocatory movements of said driving clutch member about said shaft and means for moving one of said relatively movable members to engage and disengage the clutch members.
71. A feed roll and means for intermittently rotating it, including a shaft and a friction clutch including a driven member rigid with the shaft, a driving member freely movable longitudinally and circumferentially of the shaft, and means including relatively fixed and movable screw elements for forcing the clutch members into locking engagement, in combination with means for reciprocating said driving clutch member about said shaft with a dwell at both ends of each stroke and means for relatively rotating the screw elements to engage and disengage the clutch members when the driving member is stationary at the respective ends of the stroke.
72. A feed roll and means for intermittently rotating it, including a shaft and a friction clutch including a driven member rigid with the shaft, a driving member freely movable longitudinally and circumferentially of the shaft and relatively movable members for forcing said driving member into non-slip engagement with said fixed member on the shaft, in combination with means for forcing continuous reciprocatory movements of said driving clutch member about said shaft and means for moving one of said relatively movable members to engage and disengage the clutch members.
73. A feed roll and means for intermittently rotating it, including a shaft and a friction clutch including a driven member rigid with the shaft, a driving member freely movable longitudinally and circumferentially of the shaft and relatively movable members for forcing said driving member into non-slip engagement with said fixed member on the shaft, in combination with means for forcing continuous reciprocatory movements of said driving clutch member about said shaft with a dwell at both ends of each stroke and means for moving one of said relatively movable members to engage and disengage the clutch members when the driving member is stationary at the respective ends of the stroke.
74. A feed roll and means for rotating it, including a shaft mounted vertically in suitable bearings, a friction clutch member rigid with the shaft, a brake adapted to be tightened about the exterior thereof, a driving clutch member freely movable circumferentially and longitudinally of the shaft into and out of engagement with said rigidly secured clutch member and relatively fixed and movable screw elements for forc-

ing the clutch members into engagement, in combination with means for intermittently operating said devices in sequence, including a continuously driven shaft parallel with the feed shaft and a plurality of cams thereon each having concentric portions or dwells but secured to the shaft in different phase, whereby the clutch is engaged and disengaged only when its driving element 5 is stationary at the ends of the strokes; the motion transmitting means between the cam and the screw element for rotating the latter including a rack bar forced outward by its cam to disengage the clutch members and 10 retracted by a spring to engage them; and a stop for locking one of said parts in the clutch-released position, to prevent operation of the retracting spring.

75. A metal working machine of the type 20 described, including a transverse drive shaft, a slide reciprocated thereby, punches carried by the slide, dies cooperating therewith and means for feeding bar stock transversely in the path of the punches intermittently by steps equal to the length of the desired blank; the first punch being a piercing punch, the second punch being a cut-off punch separated from the piercing punch by a distance equal approximately to the 25 length of two blanks and operating to force the severed blank rearwardly; a third punch for a further operation on the severed blank; and a reciprocating device for transferring the blank from the cut-off punch to the third punch.

76. A metal working machine of the type 30 described, including a transverse drive shaft, a slide reciprocated thereby, punches carried by the slide, dies cooperating therewith and means for feeding bar stock transversely in the path of the punches intermittently by steps equal to the length of the desired blank; the first punch being a piercing punch, the second punch being a cut-off punch separated from the piercing punch by a distance 35 equal approximately to the length of two blanks and operating to force the severed blank rearwardly; a third punch for a further operation on the severed blank; and a reciprocating device for transferring the blank from the cut-off punch to the third punch, said cut-off punch engaging the bar before the piercing punch engages it.

77. A metal working machine of the type 40 described, including a transverse drive shaft, a slide reciprocated thereby, punches carried by the slide, dies cooperating therewith and means for feeding bar stock transversely in the path of the punches intermittently by steps equal to the length of the desired blank; the first punch being a piercing punch, the second punch being a cut-off punch separated from the piercing punch by a distance 45 equal approximately to the length of two blanks and operating to force the severed blank rearwardly; a third punch for a further operation on the severed blank; and a reciprocating device for transferring the blank from the cut-off punch to the third punch, said cut-off punch engaging the bar before the piercing punch engages it.

of two blanks and operating to force the severed blank rearwardly; a third punch for a further operation on the severed blank; and a reciprocating device for transferring the blank from the cut-off punch to the third punch, said cut-off punch operating to sever 70 a blank from the end of the bar before the piercing punch engages its portion of the bar.

78. A metal working machine of the type 75 described, including a transverse drive shaft, a slide reciprocated thereby, punches carried by the slide, dies cooperating therewith and means for feeding bar stock transversely in the path of the punches intermittently by steps equal to the length of the desired blank; the first punch being a piercing punch, the second punch being a cut-off punch separated from the piercing punch by a distance equal approximately to the length 80 of two blanks and operating to force the severed blank rearwardly; a third punch for a further operation on the severed blank; and a reciprocating device for transferring the blank from the cut-off punch to the third punch, including gripper fingers for engaging 85 parallel sides of the blank and operating as a guide to support the blank in the path of said third punch.

79. A metal working machine of the type 90 described, including a transverse drive shaft, a slide reciprocated thereby, punches carried by the slide, dies cooperating therewith and means for feeding bar stock transversely in the path of the punches intermittently by steps equal to the length of the desired blank, the first punch being a piercing punch, the second punch being a cut-off punch separated from the piercing punch by a distance equal 95 approximately to the length of two blanks and operating to force the severed blank rearwardly; a third punch for a further operation on the severed blank; and a reciprocating device for transferring the blank from the cut-off punch to the third punch, including gripper fingers for engaging 100 parallel sides of the blank and operating as a guide to support the blank in the path of said third punch, said cut-off punch engaging the bar before the piercing punch engages it.

80. A metal working machine of the type 105 described, including a transverse drive shaft, a slide reciprocated thereby, punches carried by the slide, dies cooperating therewith and means for feeding bar stock transversely in the path of the punches intermittently by steps equal to the length of the desired blank; the first punch being a piercing punch, the second punch being a cut-off punch separated from the piercing punch by a distance equal approximately to the 110 length of two blanks and operating to force the severed blank rearwardly; a third punch 115

punch for a further operation on the severed blank; and a reciprocating device for transferring the blank from the cut-off punch to the third punch, including gripper fingers 5 for engaging parallel sides of the blank and operating as a guide to support the blank in the path of said third punch, said cut-off

punch operating to sever a blank from the end of the bar before the piercing punch engages its portion of the bar.

Signed at North Tonawanda, in the county of Niagara and State of New York, this 29th day of September, A. D. 1923.

CHARLES P. TOPPING.
